ELECTROSTATIC PRINTING WITH OSCILLATING SCREEN FRAME AND DUAL PRINTING AT A SINGLE STATION

James W. Edwards, Creve Coeur, Shelly W. Mays, St. Louis, and Rodney W. Stout, Webster Groves, Mo., assignors to Monsanto Company, St. Louis, Mo., a corporation of Delaware

Filed Aug. 25, 1965, Ser. No. 482,447
20 Claims. (Cl. 101—39)

This invention relates in general to certain new and useful improvements in electrostatic printing, and more particularly, to an improved automatically operable printing apparatus for electrostatic printing on a mass-production basis.

Since the advent of the thin-walled disposable containers made of plastic and synthetic resinous materials, these containers have found widespread use in the packaging industry. The vending machine industry particularly has been employing large quantities of nestable plastic containers in addition to the long-used conventional nestable paperboard containers. It is generally necessary, in this type of industry, to imprint the contents of the container, the name of the manufacturer, and/or distributor, and any other advertising and identification material on the sidewall of the container. The conventional printing methods employing offset printing techniques were not generally acceptable, because they were not adapted to mass-production operation and did not produce a desired quality of print. Because of the low profit margin on disposable containers, profits in this type of field are generally made on a volume sale basis. Accordingly, it is necessary to print containers of this type in an economically feasible manner and the containers must be printed automatically by suitable apparatus.

In an effort to find a suitable method of imprinting containers having frustro-conical shapes, there have been certain investigations in the field of electrostatic printing. However, the art of electrostatic printing is relatively new and this particular type of printing was only available for printing on flat or relatively flat items. To date, electrostatic printing techniques have not been adaptable for use in printing relative large areas on non-planar surfaces.

The presently known techniques in electrostatic printing are described in United States Letters Patent No. 3,081,698 which relates to a method of electrostatic printing by elimination of pressure or contact between the printing element and the subject material being printed. This technique involves the transfer of a liquid based ink or a resinous based ink through an electrostatic field to an image-receiving object. The ink or pigments are usually in the form of a fine powder having a particle size which is small enough to pass through the interstices of the open areas of a stencil or so-called "screen." A roller or similar mechanical device normally carries the ink particles to a point in close proximity to the stencil and where the ink is carried through the stencil by the electrostatic field to the image-receiving object. During this transfer, the ink particles are triboelectrically charged and are thus attracted toward the image-receiving object by a dielectric potential applied to the object or to a backing electrode. The charge of the particles is, of course, opposite to the backing plate and they are, therefore, accelerated through the openings or interstices in the open areas of the screen. Moreover, they are propelled toward the image-receiving object. The image-receiving object normally consists of a mandrel which is capable of retaining the article to be printed. Thereafter, the pigment will collide with and adhere to the article which is to be printed and the image is subsequently fixed by heat or solvent or a vapor or by other suitable means which are known in the prior art.

2

Since the initial development of the theory of electrostatic printing, there have been many attempts to produce devices which are capable of automatic printing. Moreover, there have been attempts to print non-linearly shaped articles by electrostatic methods. However, all of the attempts to produce these automatic and semi-automatic devices for electrostatic printing have been rather unsuccessful and commercially unfeasible for a number of reasons. All of the electrostatic printing devices thus far

employed have involved the transfer of ink across a definite and appreciable space and the particles of ink had to be physically transported across this space. However, surface tension effects on the delivery roller often prevented an even and uniform distribution of ink flow. Accordingly, the devices of the prior art had to be constructed in such manner that the field across which the particles moved had an extremely large potential difference. Moreover, the various electrodes had to be specially designed in order to prevent uneven distribution and flow of ink particles.

Moreover, the devices of the prior art were not designed with a wide range of utility, and accordingly, were not capable of printing with a wide variety of types, colors and ink particle sizes. Relatively heavy electron space currents were used to assist in the movement of ink in order to attain even distribution with various sized particles of ink. However, the relatively high ionization level at the air gap for printing, often causes arcing which interferes with and materially reduces the overall efficiency of the electrostatic printing device. Furthermore, with the devices of the prior art, it was difficult to achieve a carefully controlled quantity of electricity for effecting optimum results of the transfer of ink to the article being printed. As a result thereof, the devices of the prior art were not suitably designed for mass-production printing operations.

The substitution of a plate electrode for flat items was not an expensive or time consuming procedure when printing on relatively flat surfaces. However, there was no available technique or device which was capable of accepting a large number of mandrels or article supporting spindles. It is not a particularly difficult function to change a mandrel, but the devices presently available are not designed to accommodate mandrels of a different size or shape. Inasmuch as electrostatic screen process printing involves accurate positioning of the electrodes within a very close tolerance limit, the conventional printing apparatus of the prior art are not adaptable to electrostatic printing techniques.

It is, therefore, the primary object of the present invention to provide an electrostatic printing apparatus which is capable of electrostatically printing a large variety of articles having sizes and shapes.

It is another object of the present invention to provide an electrostatic printing apparatus and method of the type stated which is capable of achieving a high degree of printing precision on a mass-production basis.

It is a further object of the present invention to provide an electrostatic printing apparatus and method of the type stated which is characterized by simplicity, dependability, ruggedness and low cost.

It is also an object of the present invention to provide an electrostatic printing apparatus of the type stated which is capable of being altered for employment in a multi-color printing system.

It is an additional object of the present invention to provide an electrostatic printing apparatus of the type stated which is particularly adaptable to partial or complete circumferential printing on articles having curvilinear shapes.

It is another salient object of the present invention to provide an electrostatic printing apparatus and method

of the type stated where tangential approach and tangential departure is maintained between an article being printed and the screen for printing to occur along an elemental line of closest approach, for each succeeding article on a mass-production basis.

With the above and other objects in view, our invention resides in the novel features of form, construction, arrangement and combination of parts presently described and pointed out.

The art of electrostatic printing is still a recent technological innovation, and the terminology peculiar to this technology has not yet achieved a commonly acceptable and understood usage and definition. Accordingly, the term "printing" as used herein, is employed to describe the operation of a delivery of ink from the

inking member to the element being printed, although it is to be understood that the word "printing" as used herein does not connote any mechanical pressure. The word "printing" is used in its much broader sense of the word merely to mean transfer of a design from one element to another in analogous form to the use of the term "printing" in photography where mechanical pressure is not the cause of transference of the design. In interpretation of the specification and the following claims, all terminology borrowed from the conventional printing art must therefore be given a broad meaning appropriate to this specialized field of electrostatic printing.

General description

Generally speaking, the present invention relates to an apparatus which is automatic in its operation and method for electrostatic printing of conically shaped articles. The apparatus is designed to imprint desired information on the side walls of generally frusto-conically shaped containers of the nestable disposable type. However, the apparatus of the present invention is, of course, adaptable to electrostatic printing of many types and sizes of articles capable of receiving electroscopic ink. The apparatus generally comprises a base with a supporting frame constructed of standard roll-shaped channels.

Operatively mounted on the supporting frame is an electric motor for operating a screen support frame which oscillates between upper and lower positions. The screen support frame is provided with a single electrostatic printing screen and a complete upper and lower movement constitutes one printing cycle. The screen support frame is driven by a round friction gear having a flat surface or so-called "flat." The screen support frame is mounted on a drive shaft, which is, in turn, operatively connected to the electric motor. The friction gear meshes with a flange on the screen support frame and while the peripheral margin of the friction gear is in contact with the flange, the screen support frame will pivot upwardly. However, when the flat becomes aligned with the flange on the screen support frame, the frame will drop to its lower position. A pivotally mounted pneumatic cylinder is operatively connected to the screen support frame and drives the screen support frame downwardly to its lower position. The pneumatic cylinder also serves to dampen the downward movement of the screen support frame as it reaches its lower position.

The electric motor also operates a main drive shaft which, in turn, drives a primary Geneva shaft through a pair of meshing pinion gears. A primary Geneva mechanism is rigidly mounted on the primary Geneva shaft and comprises a pin-wheel with a radially extending lobe and an axially extending actuating pin. The primary Geneva mechanism is adapted to actuate a secondary Geneva mechanism which is, in turn, mounted on a secondary Geneva shaft, the latter being, in turn, operatively mounted on the supporting frame.

The secondary Geneva mechanism generally comprises a slot-wheel which is provided with four radially spaced elongated slots. Each of the slots is engageable by the actuating pin on the pin-wheel forming part of the primary Geneva mechanism. In its operation, the pin-wheel of the primary Geneva mechanism rotates approximately 270° during which time the secondary Geneva mechanism is not moved. During the last 90° rotation of the pin-wheel, which will constitute one complete revolution thereof, the actuating pin of the pin-wheel will engage a slot in the slot-wheel and rotate the slot-wheel through a 90° turn. It can be seen that the secondary Geneva shaft is, in effect, an idler shaft and is only rotatable through the actuation of the secondary Geneva mechanism by the primary Geneva mechanism.

While the drive mechanism described herein is referred to as a Geneva mechanism, including primary and secondary Geneva mechanisms, it is to be understood that the

components described herein do not comprise a true Geneva mechanism. The components described herein have been uniquely designed for purposes of this electrostatic printing apparatus. However, the terminology of the conventional Geneva mechanism has been employed as the unique drive means disclosed herein and operates on a principle similar to the operation of the conventional Geneva mechanism. Moreover, the drive means disclosed herein is adaptable for use in driving a turret having more than four positions, while the conventional four-position Geneva mechanism employed herein is a device which is capable of attaining only four positions in a 360° rotation.

A pneumatic control system is operatively mounted on the main drive shaft and is operable by the secondary Geneva mechanism. The pneumatic control system comprises a valve drum which has a pulley or sprocket affixed to one end thereof. The pulley or sprocket is operatively connected to a matching pulley or sprocket on the secondary Geneva mechanism and is operable by means of a belt or chain trained around each of the matching sprockets. The sprocket on the valve drum, however, is twice the size of the sprocket on the secondary Geneva mechanism so that rotation of the sprocket on the secondary Geneva mechanism will only rotate the sprocket on the valve drum one-half the angle of the rotation of the Geneva mechanism. The valve drum is rotatably mounted on the drive shaft and in effect, thereby forms a quill on the drive shaft. The valve drum is concentrically disposed within and in fluid communication with a valve manifold, the latter being rigidly secured to the supporting frame. The valve manifold is provided with a primary air passage or so-called vacuum passage which extends approximately through a 270° arc. The primary air passage is designed to maintain a vacuum on the valve drum in a manner hereinafter described. A secondary air passage formed by an aperture in the valve manifold is equidistantly disposed between the opposite ends of the 270° vacuum or primary air passage. The valve drum is provided with eight sets of radial and communicating axial ducts, each of which, in turn, communicates with container supporting mandrels, to be hereinafter described.

A turret is operatively mounted on one end of the valve drum and is rotatable therewith. Operatively mounted on the turret are eight sets of pillow blocks for supporting mandrel shafts and mounted on the outer end of the mandrel shafts are the container supporting mandrels. The mandrel shafts and the turret are provided with pneumatic duct work for communication with the axial ducts in the valve drum. Thus when one of the radial ducts in the valve drum is in communication with the secondary air passage, air will be supplied to the mandrel causing the container disposed on the mandrel to be ejected therefrom. When the radial duct associated with the mandrel is in communication with the primary air or vacuum passage, a vacuum is maintained on the mandrel thereby holding the container onto the mandrel.

Each of the mandrel shafts is provided at its lower end with bevel gears which match with a bevel drive gear rigidly mounted on the main drive shaft. Therefore, it can be seen that as the main drive shaft rotates, the main bevel drive gear will rotate and rotate each of the mandrel shafts and the mandrels mounted on the outer ends thereof. Moreover, the turret which holds the mandrel shafts will rotate in response to the rotation of the slot-wheel forming part of the secondary Geneva mechanism.

A suitable cup dispensing mechanism is disposed in proximate relationship to the uppermost mandrel for selectively dispensing a single container or cup and depositing the same on the mandrel as the mandrel passes the container dispensing mechanism. The placing of a container on the mandrel constitutes a first work station or so-called "loading station." Thereafter, the turret is rotated through successive 45° movements where the man-

drel is shifted to a second work station or printing station which is located approximately 90° with respect to the loading station. In the printing station, the mandrel is positioned in relationship to the printing screen where electrostatic printing on the container will take place. The screen is oscillated through a complete cycle including the upper and lower movement in the manner previously described, while the mandrel with container supported thereon is rotated in timed relation to the oscillation of the screen. The container is rotated at approximately the same rate of speed or at the same peripheral speed as the movement of the screen so that a continuing line of tangency or tangential approach and departure occurs between the surface of the container supported on the mandrel and the surface of the screen. Actual tangential contact may not occur, however, the axis of rotation of the container may be axially translated slightly to prevent any tangential contact but still maintain tangential approach and departure. An ink dispensing mechanism is disposed in close relationship to the screen on the opposite side thereof with respect to the mandrel and is designed to supply electroscopic ink to the screen at this continuing line of tangency or tangential approach. The electroscopic ink passes through the open mesh portions of the screen onto the container and thereby forms the image on the container. A unique feature of the apparatus of the present invention is that the solid space generated by the article moving around the turret intersects or approaches the printing screen in only one position, namely at the printing station so that axial translation of neither the turret nor screen is required.

After deposition of the ink image on the article, the turret is then moved through two successive 45° movements to a third work station or fixing station, permitting the image formed on the container to harden. The mandrel is thereafter rotated through two additional 45° movements to a fourth work station or discharge station where the container is aligned with a discharge tube maintained under a vacuum. The printed container is thereafter ejected from the mandrel and carried into the discharge tube for further dispatch to a conveyor or other processing station. When the mandrel then reaches the loading station again, a complete printing cycle has been performed.

The present invention also provides a modified form of electrostatic printing apparatus which employs two electrostatic printing screens. Each of these screens is mounted on opposite sides of the container supporting mandrel and is designed to shift in opposite directions. Thus when one screen shifts upwardly, the opposite screen shifts downwardly. Each of the screens is operated by a heart-shaped cam which is designed to permit this type of screen trajectory. The screens are so positioned so that the images produced thereby are marginally registered. Moreover, different colored inks can be employed with each of the electrostatic printing screens, and accordingly, multicolor printing can be employed on the second embodiment of the electrostatic printing apparatus. The modified form of electrostatic printing apparatus also provides an alternate form of driving the mandrels. The mandrels are free wheeling on the mandrel shafts and are provided with friction rollers which bear against a friction wheel, the latter being mounted on the screen drive shaft.

The present invention also provides another modified form of electrostatic printing apparatus which similarly employs two electrostatic printing screens mounted on opposite sides of the container supporting mandrel. Moreover, each of these screens is designed to shift in opposite directions where one screen will shift upwardly while the other screen shifts downwardly. The heart-shaped cam drive mechanism used to operate each of these screens is similar to the heart-shaped cam mechanism for driving the screens in the previously described

embodiment of the invention. However, in the previously described embodiment of the invention, the axis of rotation or oscillation of the electrostatic printing screen was perpendicular to the axis of rotation of the container supporting mandrel. In the present modification, the axis of oscillation or movement of the electrostatic printing screens is perpendicular to the side wall of the mandrel.

Detailed description of apparatus A

Referring now in more detail and by reference characters to the drawings which illustrate practical embodiments of the present invention, A designates an electrostatic printing apparatus generally comprising a supporting frame 1, which includes a pair of spaced longitudinally extending base channels 2, 3 provided at their corners with uprights 4. The uprights 4 are connected by a pair of upper longitudinally extending support channels 5 and the upper channels 5 and the base channels 2 are connected by transverse channels 6. Extending between each of the transverse channels 6 and being spaced between the longitudinally extending support channels 5 are a pair of transversely spaced, longitudinally extending intermediate support channels 7, 8, which are connected centrally thereof by a cross-bar 9. The channels 2, 3, 5, 6, 7 and 8, the uprights 4 and the cross-bar 9 may be formed of any suitable standard roll shape of channel, such as an I-beam shape, an H-beam shape, a standard U-beam shape or an L-beam shape as illustrated, and which is preferably formed of a relatively hard steel.

Bolted or otherwise rigidly secured to the upper surface of the longitudinally extending support channels 5 and the intermediate support channels 7, 8 are four transversely aligned pillow blocks 10, 11, 12, 13 and journaled therein is a transversely extending drive shaft 14, substantially as shown in FIGURE 2. The drive shaft 14 is held in transverse alignment within the respective pillow blocks by means of conventional washers and lock rings 15 mounted on each side of each of the respective pillow blocks. Also welded or otherwise rigidly secured to the forwardly presented support channel 5 is a mounting plate 16 for supporting a conventional variable speed electric motor 17, which is preferably of the explosion-proof type. A suitable speed reducing mechanism 18, which is conventional in its construction is connected to the main drive of the motor 17 and operatively connected to the speed reducing mechanism 18 is a V-belt pulley 19, which matches and is in longitudinal alignment with a V-belt pulley 19', the latter being keyed or otherwise secured to the main drive shaft 14. A V-belt 20 is trained around each of the pulleys 19, 19' for driving the main drive shaft 14.

Extending transversely across the intermediate support channel 7, 8 is a rotatable screen drive shaft 21 which is journaled in transversely aligned pillow blocks 22 and which are, in turn, bolted to the upper surfaces of the intermediate support channels 7, 8, in the manner as shown in FIGURE 2. The screen drive shaft 21 is suitably retained in alignment within the pillow blocks 22 by means of washers and lock rings 23 mounted on each side of each of the pillow blocks 22. Rigidly mounted on a forwardly projecting end of the screen drive shaft 21 is a sprocket 24, which is located in longitudinal alignment with a sprocket 25 mounted on the main drive shaft 14 and trained around the sprockets 24, 25 is a roller chain 26. Thus, as the electric motor 17 is energized, it will drive the main drive shaft 14 through the pulleys 19, 19' and the screen drive shaft 21 through the sprockets 24, 25.

Bolted or otherwise rigidly secured to the right transverse channel 6, reference being made to FIGURE 2, are a pair of upstanding brackets 27, which form a vertical support plate 28 and bolted thereto are a pair of transversely aligned pillow blocks 29. Extending between the pillow blocks 29 and being journaled therein is a screen support shaft 30. The shaft 30 is pivotal within the pillow

block 29 and is retained by means of conventional washers and locking nuts 31. Mounted on the shaft 30 is an oscillating screen support frame 32 having an enlarged hub 33, which is concentrically disposed about the shaft 30 and keyed thereto. The screen support frame 32 is shiftable between upper and lower limits, and a shifting movement from the lower position to an upper position, and back to a lower position constitutes one printing cycle.

The screen support frame 32 is driven by means of a friction gear or so-called "friction wheel" 34, which is mounted on the rearward end of the screen drive shaft 21 and is provided with an annular peripheral gear surface 35, which bears against and is in frictional contact with a flange 36, extending forwardly of the screen support frame 32, all as can best be seen in FIGURES 12 and 13. The friction wheel 34 is also provided with a flat surface or so-called "flat" 37 which permits downward shifting movement of the screen support frame 32, when the flat 37 becomes aligned with the flange 36. The wheel 34 is provided with an internal metal hub 38, which is, in turn, keyed to a reduced end of the shaft 21. Moreover, the friction wheel 34 is retained in position on the shaft 21 by means of a thrust washer and locking ring 39. Thus, it can be seen that as the screen drive shaft 21 rotates, the friction wheel 34 will rotate in a clockwise direction, reference being made to FIGURES 1 and 2, causing the gear surface 35 to bear against the flange 36. Clockwise rotation of the friction wheel 34 will create an upwardly directed force on the flange 36, causing the screen support frame 32 to ride and pivot about the screen support shaft 30. As the screen support frame 32 reaches its upper limit of movement, the gear surface 35 will move out of contact with the flange 36, and the flat 37 will become aligned with the flange 36. Removing the upwardly directed force on the screen support frame 32 will permit the support frame 32 to fall to its lower position.

The lowermost position of the screen support frame 32 is regulated by means of an adjustable stop 40, substantially as shown in FIGURE 13. The adjustable stop 40 generally comprises an adjustable bolt 41, which is secured to a flange 42 extending rearwardly and horizontally of the screen support frame 32. The relative position of the adjustable bolt 41 within the flange 42 can be regulated through a pair of locking nuts 43 disposed upon opposite sides of the bolt 41 with respect to the flange 42. As the screen support frame 32 shifts downwardly, the lower end of the bolt 41 will strike a bumper pad 44, which is fairly resilient and adapted to provide a cushion for the movement of the screen support frame 32. By reference to FIGURE 13, it can be seen that the bumper pad 44 is mounted on an inwardly extending bracket 45, the latter in turn being secured to the rearward support channel 5.

A pneumatic drive mechanism 46 is provided for moving the screen support frame 32 to its initial or lowermost position. The pneumatic drive mechanism is of the single acting type and generally comprises a cylinder 47 which is pivotally secured to an upright 48, the latter forming part of the supporting frame 1. The pneumatic drive mechanism 46 also includes a piston 49 which is pivotally secured to the screen support frame 32 by means of a hub 50, substantially as shown in FIGURE 13. The cylinder 47 is, of course, provided with the necessary air duct work as illustrated and which is connected through a suitable source of air pressure (not shown). Moreover, the pneumatic drive mechanism 46 is electrically connected to a conventional control mechanism (not shown) for moving the screen support frame 32 downwardly in timed relation to the other operations in the electrostatic printing apparatus A. By reference to FIGURE 1, it can be seen that the hub 50 can be secured to any of a plurality of selected apertures 51 formed in the screen support frame 32 by means of a pivot pin 52.

Thus if it is desired to increase or decrease the downward action of the drive mechanism 46, the pin 52 can be removed for shifting the hub 50 to any of the selected apertures 51.

It should be recognized that as an alternate method of driving the screen support frame, the friction wheel 34 could be eliminated and the screen support frame 32 could be driven by means of a double acting pneumatic cylinder. In this manner, the pneumatic cylinder would drive the screen support frame both upwardly and downwardly and could be controlled in timed relation to the other operations in the electrostatic printing apparatus A. The pneumatic drive mechanism 46 is generally provided inasmuch as a free fall movement of the screen support frame 32 during shifting to its lowermost position, would not be sufficiently fast for the desired speed of operation of the electrostatic printing apparatus A. However, if printing on fairly large objects were performed, the speed of operation would be substantially reduced and the screen support frame 32 could be permitted to shift to its lowermost position in a free fall. For this type of operation, the pneumatic drive mechanism 46 would be replaced by a pneumatic damper. The pneumatic damper would be similar to the conventional shock absorber and would be designed to reduce the downward movement of the screen support frame 32. Again the pneumatic damper similarly could be constructed in the same manner as the pneumatic drive mechanism and damping action could be increased or decreased by selectively positioning the hub 50 at any one of the apertures 51 by means of the pin 52. Naturally, if one of the apertures 51 near the screen support shaft 30 was selected, dampening action would be reduced. It is also possible to use a combination of roller drive and pneumatic drive mechanism for shifting the screen to upper and lower positions. During the action of shifting the screen to its uppermost position, the pneumatic cylinder would assist the wheel 34. Problems of timing would not be critical inasmuch as the roller would tend to act as a brake mechanism if the upward force created by the pneumatic drive mechanism was too great for the desired speed of operation.

The screen support frame 32 is provided with a recess 53 at its outer end for accommodating a screen retaining frame 54, the latter being secured to the screen support frame 32 by means of bolts 55. The screen retaining frame 54 is designed to retain an electrostatic printing screen 56 and is so designed so that electrostatic printing screens 56 may be easily removed and inserted therein when it is desired to change the printing design. Furthermore, by reference to FIGURE 1, it can be seen that the screen retaining frame 54 is arcuately shaped and has an arcuate distance of approximately 45° with respect to the screen support shaft 30. Furthermore, the screen 56 is arcuately shaped or "curvilinear" about an axis which is perpendicular to the first axis of rotation forming the arcuate shape, for reasons which will presently more fully appear.

The electrostatic printing screen 56 is generally formed of a fine mesh conductive material or a material which is rendered conductive and wherein the non-printing areas are suitably masked. The non-masked portion or printing areas of the screen 56 is designed to permit pigments in the form of ink powders to pass through the interstices of the open areas. The screen 56 may be constructed by any of the presently known methods of making electrostatic printing screens. One particularly effective screen is provided where the mesh material is stainless steel with 250 wires to the inch. This screen element is then provided with a photosensitive coating so that it spans all of the interstices of the screen. The sensitized screen is then exposed to an arc which is preferably rich in ultraviolet light, through an interposed positive image of the desired copy. Exposure to the light is maintained for a time which is sufficient to harden the areas where the interposed image transmits light. The coated screen is

then developed to dissolve the areas of the coating which were protected from the light by the opaque areas of the film image, thereby leaving a solid mask in the areas affected by the light.

5 Various methods of preparing the screen can be used. It is only necessary that the non-printing area be effectively masked to prevent the movement of pigment therethrough in subsequent electrostatic printing operation. This is accomplished very well by various known methods 10 as well as the use of photosensitive coatings on the open mesh. Techniques familiar in the screen-silk process printing may also be employed in the production of stencils or screens for electrostatic printing operation. It is not necessary to have the regularity of openings of a fine mesh 15 screen or sensitized net. The regular openings in fibrous materials and the like can be satisfactory as long as the openings in the particle size of the pigment are compatible for movement therethrough.

In many electrostatic printing operations which can be 20 performed with the apparatus of the present invention, it has been found to be desirable to use a curved electrostatic printing screen. The screen 56 may also be manufactured or produced in the manner as described in my copending application Serial No. 463,251, filed June 11, 25 1965, and which relates to the method of producing curved electrostatic screens. In this method, a photosensitive emulsion is applied to a wire mesh support and held in a screen chase. The screen is then exposed to light through a photographic negative of the required print or design to 30 be ultimately imprinted upon a substrate. A washout of the exposed emulsion leaves a positive image on the screen which can be subsequently converted to a negative image required for printing by means of electroplating. The plating adheres preferentially to the open mesh 35 portions of the screen. Subsequent treatment with an emulsion remover such as hydrogen peroxide and various acid etches will clear the print areas leaving a negative screen in which the non-print areas have interstices filled with metal. The plating metal is chosen to give a final 40 screen which is rigid but formable by various forming methods such as rolling and drawing. The final screen thereafter can be shaped into a desired surface which will parallel complex surfaces to be printed.

Extending between the intermediate support channels 45 7, 8 is an ink feeding mechanism support frame 57 for retaining a suitable air operated ink feeding mechanism 58 of the type described in copending application Serial No. 461,044, filed June 3, 1965. It has been found in connection with the present invention that an air operated 50 ink feeding mechanism provides substantially superior results with certain electroscopic inks of low thermal softening point due to the fact that the electroscopic ink particles in these inks are relatively small and extremely light in weight. Moreover, they are readily compressible 55 and very difficult to control. Particles of this type have a tendency to cling together in agglomerates and due to the resinous nature thereof tend to become permanently bonded when subjected to even moderate compression. Many mechanical systems for delivering electroscopic ink 60 create undesirable situations in that heat and friction have been generated at the place of contact between the mechanical mechanism, such as the rotating brush and the image screen or other transfer media. Furthermore, the inks which are used in this type of system are thermoplastic in nature and, therefore, are sensitive to both heat and pressure with regard to softening and fusing. Consequently, it has been found that the air operated ink feeding mechanism of the type described substantially eliminates 65 the various problems in ink delivery which have been present in the devices of the prior art.

The air operated ink feeding mechanism 58 is preferably provided with a suitable positioning mechanism for accurately positioning the ink feeding mechanism 58 with regard to the electrostatic printing screen 56. The 70 air operated ink feeding mechanism 58 also includes a

hopper 59 which deposits ink in an ink delivery tube 60. The ink delivery tube is provided with a discharge nozzle 61 which terminates in close proximity to the electrostatic printing screen 56, substantially as shown in FIGURES 2 and 11. By further reference to FIGURE 11, it can be seen that the discharge nozzle 61 has a relatively small height and a relatively wide width. In fact, it can be seen that the width of the discharge nozzle 61 is approximately equal to the width of the electrostatic printing screen 56. Furthermore, the air gap between the terminal end of the discharge nozzle 61 and the surface of the electrostatic printing screen 56 is only about 0.005" to 0.12". For the purposes of the present invention, it has been found that when the discharge nozzle 61 is produced with a height relative to the direction in which the screen moves within the range of $\frac{1}{16}$ " to $\frac{1}{4}$ ", optimum results have been obtained.

The ink feeding mechanism 58 is also provided for an air removal system (not shown) for removing the fluid which carries the ink particles to the electrostatic printing screen 56. If the air was forced through the openings of the screen or designed to carry the ink particles through the open portions of the screen, the final print would become blurred. The air removal system is designed to reduce the air velocity to substantially zero at the discharge nozzle 61 so the ink particles, which are triboelectrically charged, will be carried by an electrostatic field. The ink feeding mechanism herein described also includes a triboelectric charging chamber where the ink particles are bombarded against a metal wall and become triboelectrically charged. The ink feeding mechanism 58 is, however, more fully described in said copending application Serial No. 461,044, filed June 3, 1965 and is, therefore, not described in detail herein.

It is possible to use a belt-feed type of ink delivery system of the type described in copending application Serial No. 453,706, filed May 6, 1965, which is also efficiently employed in electrostatic printing operations of the type performed by the apparatus A. This type of electrostatic printing apparatus includes a hopper for containing the desired electroscopic ink and rotatably mounted in the hopper is a continuously moving agitator for keeping the ink particles in a suspended or levitated state. A distributor roller is disposed beneath the hopper and communicates internally therewith to receive a charge of ink and deposit the same on a continuously rotating belt. The distributor roller in combination with the agitator of the hopper also functions as a metering roller for metering a preselected charge of the ink. Provided for operative communication with the surface of the belt is a charging roller with a surface speed different from the surface speed of the belt. The charging roller also aids in providing an even distribution of ink particles transversely across the belt and for creating a triboelectric charge on the ink particles contained on the surface of the belt. The belt is driven by a pair of rollers, one of which is charged and serves as the discharge electrode in the electrostatic printing system. This type of feeding mechanism is also provided with a series of suitable adjustments in order to vary dimensions and distance between the moving parts, which are essential for providing a wide degree of utility so that the feeding mechanism and hence the electrostatic printing apparatus A is capable of handling a wide variety of types and sizes of electroscopic inks.

Any of a variety of electroscopic inks can be employed in the present invention. Generally, the electroscopic inks comprise a finely dispersed powder which is capable of being triboelectrically charged. The powder generally carries a desired pigment. A number of satisfactory powders can be employed in the present invention and each must be in a finely divided state. Suitable powders are dyed thermoadhesive resins such as rosin, gum copal, gum sandarac, ethyl cellulose, Egyptian asphalt and the like. A very satisfactory thermoadhesive powder can be

produced by dissolving equal parts of ethyl cellulose and Vinsol resin in acetone together with a small amount of spirit soluble aniline dye such as Nigrosine or aniline blue and spray drying the solution to produce an extremely fine powder having substantially spherical particles. Dyed Lycopodium powder is suitable where thermoadhesive properties are not required of the powder, as is also starch, cellulose flour, powdered metal and copper powder.

Whether fusible, thermoadhesive or non-fusible powders or others are used, the particle size is preferably near the limit of definition of the eye under ordinary reading conditions. Excessive powder size contributes to graininess in appearance of the image. On the other hand, extremely fine powder may be undesirable in many instances due to its tendency to "ball up" or cling together in clusters. It is, therefore, desirable to use a powder in which substantially all the particles are within the size range from 2 to 20 microns. If spherical powders are used, this refers to their diameters, otherwise to the largest dimension. For most purposes, it is preferred to use an equidimensional powder particle, the sphere being the preferred form.

Bolted or otherwise rigidly secured to the undersurface 25 of each of the intermediate support channels 7, 8 directly beneath the pillow blocks 11, 12 are a pair of transversely aligned pillow blocks 62 for journaling a primary Geneva shaft 63. The primary Geneva shaft 63 is retained in transversely aligned position by means of washers and 30 lock rings 64 mounted on each side of each of the pillow blocks 62. Keyed or otherwise rigidly secured to the primary Geneva shaft 63 is a pinion gear 65, which meshes with a driving pinion gear 66 mounted on the main drive shaft 14. Thus as the main drive shaft 14 35 is rotated, the primary Geneva shaft 63 will be continuously rotated through the action of the meshing pinion gears 65, 66. The pinion gears 65, 66 are conventionally provided with hubs 67 for mounting on their respective shafts 63, 14 and the hubs 67 may be provided with keys or set screws (not shown) for securing the pinion gears 65, 66 to their respective shafts.

Mounted on the rearward end of the primary Geneva shaft 63 is a primary Geneva mechanism 68 which generally comprises a pin-wheel or so-called "pin-gear" 69. 45 The pin-wheel 69 is generally circular in cross section and is provided with an outwardly extending lobe 70 and mounted on the lobe 70 is an axially extending actuator pin 71. By reference to FIGURES 8 and 9, it can be seen that the lobe 70 is somewhat triangularly shaped and extends beyond the line which would form the 50 peripheral margin of a truly circular wheel. The pin-wheel 69 is also provided in the area of the lobe 70 with a quarter-round or arcuate recess 72 having an arcuate guide wall 73.

55 Similarly journaled in a pair of transversely aligned pillow blocks 74 which are bolted to the upper surfaces of the intermediate support channels 7, 8 is a transversely extending secondary Geneva shaft 75. The shaft 75 is spaced to the left of and extends in parallel relation to the primary Geneva shaft 63 and the main drive shaft 14. Furthermore by reference to FIGURES 1 and 3, it can be seen that the secondary Geneva shaft 75 is disposed within approximately the same horizontal plane as the main drive shaft 14. However, it is to be noted that the primary Geneva shaft 63 is disposed beneath the main drive shaft 14 and the secondary Geneva shaft 75, as illustrated in FIGURE 3. Rigidly mounted on the secondary Geneva shaft 75 and being rotatable therewith is a secondary Geneva mechanism 76 which generally comprises a slot-wheel or so-called "star-wheel" 77. The slot-wheel is provided with four outwardly extending radially spaced crowns 78, which are connected by arcuately shaped webs 79. Thus by reference to FIGURE 4, it can be seen that each of the crowns 78 is spaced at 90° intervals and are connected by the arcuately shaped

webs 79. The radius of curvature of the arcuately shaped webs 79 is substantially equal to the radius of the pin-wheel 69 for reasons which will presently more fully appear. Each of the crowns 78 is provided with relatively deep pin-engaging slots 80 and which are sized to accommodate the actuator pin 71. By reference to FIGURE 4, it can be seen that the webs 79 are provided with arcuately shaped concave guide surfaces 81. By further reference to FIGURES 4 and 10, it can be seen that the slots 80 are sufficiently deep so that the actuator pin 71 is extended therein to the full length of the guide slot 80 when the crown 78 of the slot-wheel 77 are engaged with the guide wall 73 of the pin-wheel 69. Thus by further reference to FIGURES 4, 9 and 10, it can be seen that the concave guide surfaces 81 are formed with the same radius of curvature as the outer peripheral wall of the pin-wheel 69.

The electrostatic printing apparatus A also includes a pneumatic control system 82, which comprises a valve drum 83 concentrically disposed about the main drive shaft 14 in a free wheeling relationship with respect thereto. The valve drum 83 is also concentrically disposed within a valve manifold 84, the latter being rigidly secured to a pair of L-shaped brackets 85 which are in turn, secured to the upper surface of the intermediate support channel 8. Secured to the forward end of the valve drum 83 by means of bolts 86 is a sprocket 87, which is longitudinally aligned with a sprocket 88, the latter being secured to the rearward face of the slot-wheel 77 by means of bolts 89, and trained around the sprockets 87, 88 is a drive chain 90. Thus when the secondary Geneva mechanism 76 is rotated through the action of the primary Geneva mechanism 68, the valve drum 83 will be rotated therewith. Also secured to the forward face of the sprocket 87 through the bolts 86 is a roller bearing 91. Rigidly secured to or integrally formed with the rearward face of the valve drum 83 is a turret plate or so-called "turret" 92. Also secured to the turret plate 92 by means of bolts 93 is a roller bearing 94. In this manner, it can be seen that the valve drum 83 and the turret 92 carried therewith is rotatable on a free wheeling relationship with respect to the main drive shaft 14. Furthermore, the valve drum 83 and the turret 92 are rotatable with the slot-wheel 77 for reasons which will presently more fully appear.

It should be recognized that the component 68 is termed "a primary Geneva mechanism," and the component 76 is termed a "secondary Geneva mechanism," whereas in fact, these two components do not form a true Geneva mechanism. However, the terminology of the conventional Geneva mechanism has been employed as the unique drive disclosed herein operates on a principle similar to the operation of the conventional Geneva mechanism. Nevertheless, it is pointed out that the drive mechanism provided herein is not the conventional well known Geneva mechanism.

The rotation of the transversely extending drive shaft 14 will rotate the pinion gear 66 which will, in turn, rotate the pinion gear 65 and the primary Geneva shaft 63. Thus, it can be seen that as the main drive shaft 14 is continually rotated, the primary Geneva shaft 63 will be continually rotated. Rotation of the primary Geneva shaft 63 will cause the pin-wheel 69 to rotate in a counterclockwise direction, reference being made to FIGURE 4. As this occurs, the annular side wall of the pin-wheel 69 will be slightly spaced from the concave guide surfaces 81 in one quadrant. Inasmuch as the guide surface 81 has the same radius of curvature as the annular surface of the pin-wheel 69, the secondary Geneva mechanism 76 and the slot-wheel 77 will not rotate on the secondary Geneva shaft 75. Continued rotation of the pin-wheel 69 in the counterclockwise direction will cause the outwardly extending actuating pin 71 to engage a slot 80 in the next adjacent crown 78. Engagement of a pin 71 in this slot 80 is more fully shown in FIGURE 75

4 as the pin 71 begins to enter the slot 80. Continued rotation of the pin-wheel 69 will cause the slot-wheel 77 to rotate in a clockwise direction, reference being made to FIGURE 4 until the pin 71 reaches a position where it sits immediately beneath the lowermost slot 80 in the slot-wheel 77. It can be seen that the pin-wheel 69 rotates for approximately 270° during the time that the slot-wheel 77 remains in a stationary position. The additional 90° rotation of the pin-wheel 69 through a 90° angle will cause the pin 71 to move inwardly in one of the slots 80 and cause the slot-wheel 77 to rotate in a clockwise direction through a 90° angle until the pin 71 moves downwardly in the slot 80.

As the slot-wheel 77 on the secondary Geneva shaft 75 is rotated through a 90° arc, the gear drive chain 90 trained around the sprockets 87, 88 will cause the valve drum 83 and the turret 92 to rotate. However since the sprocket 87 is twice the diametral size of the sprocket 88, the valve drum 83 and the turret 92 will only rotate one half the angle of the 90° arc or 45°. Hence, for every 90° rotation of the secondary Geneva mechanism 76, the turret will rotate 45°. Accordingly, the turret is an eight position turret which is actuated by a four position Geneva mechanism.

25 The modified Geneva mechanism can be adapted to other values of multiplicity for the number of stops per revolution of the turret 92. The following general relationship governs the adaptation of multiplicity to the modified Geneva mechanism. In the following relationship n_t represents the number of stations on the turret 92, n_g represents the number of slots on the slot-wheel 77 of the secondary Geneva mechanism, N_g represents the number of teeth on the sprocket 88 attached to the secondary Geneva mechanism; and N_t represents the number of teeth on the sprocket 87 directly attached to the turret 92. The relationship governing this adaptation of multiplicity is therefore:

$$n_t = \frac{n_g N_t}{N_g}$$

40 Thus for a given n_g , a wide range of multiplicity is possible by varying N_t and N_g or corresponding diameters of pulleys or gears.

Bolted to the rearward face of the turret 92 are eight pairs of radially aligned bearing blocks 95, 96 for rotatably supporting mandrel shafts 97. Each of the mandrel shafts 97 is provided at its lower end with bevel gears 98, which mesh with an enlarged bevel gear or spiral gear 99, the latter being mounted on the rearward end of the main drive shaft 14, substantially as shown in FIGURES 2 and 7. As the enlarged bevel gear or spiral gear continuously rotates with the main drive shaft 14, each of the mandrel shafts 97 will be continuously rotated as the bevel gears 98 are in continuous meshing engagement with the spiral gear 99.

55 Welded to the outer end of each of the mandrel shafts 97 is a mounting plate 100 and bolted to each of the mounting plates 100 are conically shaped container supporting mandrels 101 which are more fully illustrated in FIGURE 11. The container supporting mandrel 101 is generally formed of a frustro-conical shape and has an annular tapering side wall 102, and a hollow interior forming an axial chamber 103. The mandrel 101 is also provided with a relatively flat centrally apertured end wall 104 and which abuts against the mounting plate 100 in the manner as shown in FIGURE 11. It can be seen that the mandrel 101 is secured to the mounting plate 100 by means of screws 105. By this construction, it is possible to easily remove the screws 105 for changing of any of the mandrels 101. The mandrel 101 is also provided with a concave end wall 106, which is centrally apertured and in communication with the axial chamber 103. Moreover, by further reference to FIGURE 11, it can be seen that the axial chamber 103 communicates with a fluid duct 107 in the hollow mandrel shafts 97.

The end wall 106 is integrally formed with a plurality of radially spaced axially extending container engaging fingers 108 for engaging the bottom wall of a container C, which may be disposed thereon. The container engaging fingers 108 are designed to engage the bottom wall of the container C in order to prevent collapsing thereof when a vacuum is applied to the mandrel shaft 97 and to the mandrel 101.

The container supporting mandrel 101 is designed to accommodate disposal, nestable, thin-walled plastic cups of the type which are commercially available and usually found in vending machines. However, it should be understood that the mandrel 101 can be readily removed and replaced with a similar mandrel accommodating cups or containers of a different size or shape by merely removing the screws 105. In this connection, it should be obvious that it is possible to provide mandrels to accommodate such containers as ice cream containers, cheese container, or any similar open-ended container of this type. Moreover, it should be understood that the present invention is not limited to printing of plastic containers but can be employed to suitably imprint containers formed of paper, paperboard, etc.

The apparatus of the present invention is capable of exhibiting a wide degree of utility through its versatility of operation. When printing various size containers, the mandrels 101 can be replaced. Moreover, the screen support frame 32 can be axially translated to oscillate in a different plane for accommodating larger or smaller sized mandrels. Similarly, the ink feeding mechanism 58 can be axially translated for accurate positioning with respect to the screen support frame 32. Details of providing axial translation of the above components are conventional and are, therefore, not described in further detail herein.

By reference to FIGURES 5 and 11, it can be seen that each of the mandrels 101 become aligned with the electrostatic printing screen 56. Thus, it can be seen that the annular side wall 102 parallels the surface of the electrostatic printing screen 56. Through this positioning, it is possible to employ the principles of electrostatic printing on curved surfaces in the manner described in copending application Serial No. 472,829 filed July 19, 1965. In the printing of curvilinear shaped surfaces such as on conically shaped containers, the container is positioned in an axis of rotation so that the exterior wall thereof tangentially approaches and departs from the screen. Thus, printing will occur along an elemental line of closest approach between the container and the electrostatic printing screen. Moreover, the mandrel 101 with the container C supported thereon is rotated at approximately the same rate of speed or at the same peripheral speed as the oscillating movement of the screen 56 so that a continuing line of tangency occurs between the surface of the container C supported on the mandrel 101 and the surface of the electrostatic printing screen 56.

By reference to FIGURE 2, it can be seen that the screen retaining frame 54 and hence the electrostatic printing screen 56 is not perpendicular to the axis of rotation of said frame. Accordingly while the screen 56 is arcuately shaped in one plane, that is a plane parallel to the side wall of the mandrel 101, is it also arcuately shaped about an axis which is axially translated from and parallel to the side wall of the mandrel 101. This screen is often referred to as a conically shaped screen and is oscillated or rotated in timed relation to the rotation of the mandrel 101 so that each of the two elements tangentially approaches and tangentially departs along a continuing line of closest approach. However, it should be understood that a relatively flat screen, that is a screen which lies in a relatively flat plane parallel to the side wall of the mandrel 101, could be employed if the axis of rotation or oscillation of said screen was directly perpendicular to the side wall of the mandrel 101. However, by reference to FIGURE 2, it can be seen that the axis

of oscillation or movement of the screen 56 is directly perpendicular to the axial centerline of the mandrel 101 and accordingly, the curved screen must be employed.

Simultaneously with the rotation of the container C supported on the mandrel 101 and the oscillation of the screen support frame 32 electroscopic ink will be passed through the screen 56 to the container C in a manner hereinafter described in more detail. The ink particles will pass through the screen 56 along this line or band of tangency. In this manner, it is possible to provide electrostatically printed images on the surface of a curvilinearly shaped article, such as conically shaped container.

By the process of the present invention, and by using the techniques employed in said copending application Serial No. 472,829 filed July 19, 1965, it is also possible to use contact electrostatic printing between the substrate and the electrostatic printing screen. In this process, the flat surface or the container C is retained in very light tangential contact with the surface of the electrostatic printing screen. Both the screen and the container are moved so that a line of continuing light tangential contact is maintained therebetween and electroscopic ink is applied through the screen to the container at this line of tangential contact. Thus, it should be understood that each of the bevel gears 98 is sized so that the speed of rotation of the mandrel 101 is such that it has the same peripheral speed as the movement of the oscillating screen support frame 32 and the electrostatic printing screen 56.

It is possible to synchronize the rotation of the mandrels 101 with the screen support frame 32 by means of the mechanism described in our copending application Serial No. 482,475, filed Aug. 25, 1965, wherein a friction driven free-wheeling mandrel is employed. In this mechanism, the bevel gears 98 on each of the mandrel support shafts 97 could be eliminated. Furthermore, the outer ends of each of the mandrel support shafts would be provided with bearings for rotatably mounting the mandrels. Each of the mandrels will be provided with a friction wheel for meshing engagement with a drive wheel operatively mounted on the screen drive shaft 21. Moreover, a variable speed transmission in the form of a variable belt drive trained around the sprockets 24, 25 could be employed. However, the gear drive mechanism of the present invention is the preferred embodiment inasmuch as the possibility of slippage is substantially reduced.

The pneumatic control system 82 is more fully illustrated in FIGURES 5, 6 and 8, and as previously indicated, includes the rotatable valve drum 83 and the valve manifold 84. The valve manifold 84 is cylindrical and is sized to snugly and yet rotatably accommodate the valve drum 83. By reference to FIGURE 8, it can be seen that a pair of washers and lock rings 109 are disposed on opposite sides of the valve manifold 84 and which bear against the annular side walls of the manifold 84 for holding the latter in axial alignment with the valve drum 83. Furthermore, it can be seen that the valve drum 83 is annularly grooved in the provision of a pair of annular slots to accommodate sealing rings 110. The sealing rings 110 may be formed of any suitable material normally employed in the manufacture of sealing rings, such as neoprene rubber.

The valve manifold 84 is provided on its interior surface with a primary air passage or recess 111. The primary air passage 111 is generally maintained under conditions of reduced air pressure and for the purposes of the present invention is often referred to as a "vacuum passage." A suitable source of air under reduced pressure (not shown) may be supplied to the primary air passage 111 through a tube 112 connected to a fitting 113, which is in turn connected to the valve manifold 84. The fitting 113 and tube 112 communicate with the primary air passage 111 in the manner as shown in FIGURE 5. By further reference to FIGURE 5, it can be

seen that the primary air passage 111 extends for approximately 270°. A secondary air tube 114 is connected to a fitting 115 which in turn communicates with the valve drum 83 in a manner to be hereinafter described in detail. The secondary air tube or air line 114 is connected to a suitable source of air pressure (not shown) for providing positive fluid pressure to the valve drum 83 in a manner also hereinafter to be described in more detail.

The valve manifold 83 and the turret 92 are so positioned with respect to the secondary Geneva mechanism 76 so that the primary air passage 111 remains in contact with seven of eight radially spaced, radially extending fluid ducts 116. By reference to FIGURES 5 and 8, it can be seen that the eight radially extending fluid ducts 116 each communicates with the surface of the valve drum 83. Moreover, the first and seventh radial fluid ducts 116 communicate with the ends of the primary air passage 111. The eighth radial fluid duct 116 thereby remains in communication with the secondary air tube or air line 114. By reference to FIGURES 8, 9 and 10 which show the operative connection between the pneumatic control system 82, the primary Geneva mechanism 68, and the secondary Geneva mechanism 76, it can be seen that the valve drum 83 is located so that it stops in a position where one radial fluid duct 116 is always located in communication with the secondary air line 114 as the secondary Geneva mechanism 76 rotates through a complete 90° revolution. The eight radially spaced fluid ducts 116 in the valve drum 83 in turn, communicate with eight axially extending fluid ducts 117, also formed in the valve drum 83.

Integrally formed with the rearward end of the valve drum 83 is a diametrically enlarged circular plate 118 which is held in fluid-tight communication with the forwardly presented surface of the turret 92 by means of an annular sealing ring 119. The circular plate 118 is provided with radially extending fluid ducts 120, which in turn communicate with a hollow fluid channel 121 formed in the bearing block 96. By reference to FIGURES 7 and 8, it can be seen that the bearing blocks 96 are not the same as the bearing block 95. The bearing block 95 is a conventional thrust bearing which includes an annular type bushing for retaining the mandrel shaft 97. The bearing block 96, however, includes a bushing 122, which is cut away in the provision of an annular fluid duct 123, and which, in turn, is maintained in continual communication with the hollow fluid channel 121. The fluid duct 123 in turn communicates with the fluid duct 107 formed in the mandrel shafts 97 through a pair of connecting fluid ducts 124.

By means of the above outlined construction, the mandrel 101 is maintained in fluid communication with the primary air passage 111 in the valve manifold 84 and the secondary air line 114. Thus, when the valve drum 83 is located in the position as shown in FIGURE 5, seven of the radial ducts 116 in the valve drum will be in communication with the primary air passage 114, causing a reduced air pressure through the radial fluid ducts 116, and the axial ducts 117. Inasmuch as the axial fluid ducts 117 communicate with the radially extending fluid ducts 120, the hollow fluid channels 121 and the fluid channels in the bearing blocks 96 and the fluid ducts 107 in the mandrel shaft, fluid communication is maintained between the valve manifold 84 and the mandrel 101. Accordingly, a container C disposed upon the mandrel 101 will be retained thereon by means of a vacuum on the mandrel 101. Similarly, air pressure may be supplied to the mandrel 101, which is in communication with the secondary air line 114, where a container C on the mandrel 101 will be ejected therefrom.

By further reference to FIGURE 1, it can be seen that the mandrel 101, which is located in communication with the secondary air tube 114 is positioned in alignment

with a discharge tube 125. The discharge tube 125 is maintained under a vacuum by a suitable vacuum source (not shown) in order to carry the containers disposed in the discharge tube to a suitable collection area (also not shown). Thus, when the mandrel 101 is maintained under a positive pressure, the container C disposed thereon is ejected and deposited into the discharge tube 125. Inasmuch as the discharge tube 125 is maintained under vacuum conditions, the container C is thereupon carried to a suitable collection area.

The electrostatic printing apparatus A also includes a container dispensing mechanism 126 for intermittently dispensing or depositing containers C on each of the mandrels 101 as they pass the dispensing mechanism 126. The container dispensing mechanism 126 is vertically positioned and is disposed above the mandrel 101 as it reaches its upper most position, reference being made to FIGURE 1. The container dispensing mechanism is similar to the mechanism described in our co-pending application Serial No. 482,475, filed Aug. 25, 1965, and is designed to dispense a single container pursuant to a control signal. A simple control circuit (not shown) may be provided for actuating a solenoid on the container dispensing mechanism 126 pursuant to a positioning of a mandrel 101 in alignment with the dispensing mechanism 126. Furthermore, by reference to FIGURES 1 and 5, it can be seen that the mandrel 101, which is positioned beneath the container dispensing mechanism 126 is maintained in fluid communication with the primary air passage 111, thereby creating a condition of reduced pressure or a vacuum on the mandrel 101. Thus as the container C is dispensed from the mechanism 126, it will be deposited on the mandrel and retained thereon due to the vacuum maintained across the mandrel 101.

An ink fixing tank 127 is also mounted on the frame 1 and is disposed between two lower longitudinal base channels 2, 3 in the manner as shown in FIGURES 1 and 3. The method of fixing the electrostatic printing image is not critical to the present invention and various well known methods in the prior art can be employed, such as the fixing by means of heat or selectively filtered radiation. However, it has been found that solvent vapor fixing of electrostatic printing images has proved to be one of the most effective methods of permanently fixing electroscopic ink on a substrate. In solvent vapor fixing, it is often desirable to construct the solvent tank with cooling coils in order to prevent any of the vapor from escaping into the atmosphere. The cooling coils surrounding the tank, generally along the upper margin, will cause any escaping vapors to condense and drain back into the liquid bath and then become vaporized. The choice of the solvent depends upon the composition of the powder images to be fixed. With powders formed of pigmented rosin, copal, asphalt and other natural resins as well as several synthetic resins and plastics, such as cellulose, a desirable solvent is trichlorethylene. Amyl-acetate or butylacetate can likewise be used with many resins. Also butyl alcohol and perchloroethylene are particularly useful as they are somewhat less volatile.

It is generally desirable to maintain the solvent in the form of a saturated vapor, where the solvent is held at its boiling point. Fusion of the powder image much more readily takes place provided that the powder is soluble in a solvent. In the fixing chamber, the solvent from the vapor phase condenses on the printed article and is absorbed in the ink powder, causing it to soften and coalesce to a continuous film and adhere to the article. It is necessary to adjust the degree of saturation of the solvent vapor and exposure time in order to obtain coalescence and adhesion without absorbing enough solvent to cause excessive liquefaction and running of the images. The fusing time in solvent vapor fixing is not usually critical, whereas it may be with heat fusing of thermoplastic based ink on plastic articles. When the

substrate is then removed from the vapor chamber, the solvent evaporates from the image and the image solidifies and becomes permanently bonded or fixed onto the substrate in a matter of a few seconds.

By reference to FIGURE 1, it can be seen that the mandrel 101 is moved to its lowermost position when it is introduced into the ink fixing tank 127. Continued rotation of the turret 92 in a clockwise direction, reference being made to FIGURE 1 removes the mandrel 101 from the ink fixing tank permitting the container disposed thereon to air dry. Generally, the time required for the movement of the mandrel through three successive 45° movements to the discharge position where it is in alignment with the discharge tube 125 provides sufficient time for evaporation of the solvent, so that the image on the container C is permanently hardened.

By reference to FIGURE 1, it can be seen that the electrostatic printing apparatus A is so constituted and arranged that there are, in effect, five work stations which are located in a 360° circle, namely the arcuate movement of at least one mandrel 101 in a full cycle. It can be seen that each of the mandrels 101 rotates in a clockwise direction, reference being made to FIGURE 1, and that each printing cycle actually starts at the point where the mandrel 101 is in horizontal alignment with the container dispensing mechanism 126. Thus, the dispensing of a container C on a mandrel 100, which is located at the container dispensing mechanism 126 constitutes a first work station or so-called "loading station" S₁. As the mandrel 101 with the container C supported thereon moves in a clockwise direction to the screen support frame 32, it is moved into a printing position for receiving a desired printed image. The printing of the container C at the screen support frame 32 constitutes a second work station or so-called "printing station" S₂. It can be seen that the printing station S₂ is located at two successive 45° positions in a clockwise direction from the loading station S₁. After the container C has received the electrostatic printing image from the work station S₂, it is transferred to a fixing station S₃, which constitutes a third work station. After the container is introduced into the solvent vapor at the fixing station S₃, the mandrel is again rotated through three successive 45° movements until it becomes aligned with the discharge tube 125. During the time that it passes through two successive 45° movements after introduction into the fixing tank 127, it is positioned in a so-called "drying station" or fourth work station, S₄. Sufficient time is provided for release of the solvent contained in the ink on the image by air drying during the time that the container C is positioned at the drying station S₄. The positioning of the mandrel 101 at the discharge tube 125 constitutes a fifth work station or so-called discharge station S₅, where the container is ejected from the mandrel 101.

It should be recognized that an electrostatic field is maintained between the electrostatic printing screen 56 and each of the mandrels 101. The apparatus A may be conventionally provided with the necessary insulating sleeves and washers and electrical circuit necessary to provide the electrostatic field. This type of construction is conventional and is, therefore, neither illustrated nor described in detail herein. However, it should be pointed out that while current requirements for electrostatic printing of the type herein employed are not heavy in the ordinary sense, a very definite electron current or space current flows across the printing space during the printing operation. It is desirable to have a space current of at least 1 to 2 milliamperes per square inch of printing area. Moreover, the high potential source should be capable of maintaining a desired voltage under current drains in the range of approximately 100 milliamperes or slightly more.

The ink feeding mechanism 58 may also be electrically charged to serve as one of the elements forming the electrostatic field. In actuality, the feeding tube 60 of the ink feeding mechanism 58 would be the element to

be established as an electrode. However, any metallic electrode in close proximity to the discharge end or nozzle 61 of the ink feeding tube 60 could serve as an electrode. In the event that the ink feeding mechanism 58 is employed as one of the poles or electrodes forming the electrostatic field, the ink hopper 59 would be insulated from the remainder of the ink feeding mechanism. The mandrel 101, screen 56 and ink delivery tube 60 are charged in such manner so that an electric field existing therebetween is in the form of a potential gradient. The direction of the potential gradient depends on the charge of the ink particle. If the ink particles are charged positively, the electric field will create a negative charge or less positive charge on the mandrel 101. Generally, an ideal situation exists where the mandrel can be charged in one polarity, the ink delivery tube charged at the opposite polarity and the screen maintained at ground polarity. Thus, if the ink particles were positively charged, the mandrel 101 would be negatively charged and similarly, if the ink particles were negatively charged, the mandrel 101 would be positively charged. It is not necessary to have a positive-negative type potential gradient existing between the three aforementioned components. The potential gradient which exists may be either wholly positive or negative. Thus if the ink particles were positively charged, the ink delivery tube 60, the screen 56 and the mandrel 101 could have successively less positive charges so that a potential gradient still exists and where this current is capable of moving the triboelectrically charged ink particles from the delivery tube 60 through the screen 56 and to the mandrel 101.

The electrical circuitry may include a high voltage reversing switch (not shown) which is designed to reverse the potential gradient existing between the delivery tube 60, the screen 56 and the mandrel 101. For example, if the mandrel 101 were positive and the delivery tube 60 were negative, position reversal of the switch would cause the mandrel 101 to be charged negatively and the delivery tube 60 to be charged positively. If on the other hand, the potential gradient which existed was all of one charge, position reversal of the switch would reverse the direction of the potential gradient. In this manner, the direction of the lines of force of the electrostatic field which exists between these various components may be reversed. This type of reversal would occur after each printing cycle so that any excess ink which is gathered on the screen would be automatically removed therefrom prior to the start of the next printing cycle with the last named screen.

Operation of Apparatus A

In use, the ink hopper 59 is filled with a desired electroscopic ink. The electroscopic ink has been previously fluidized as indicated above by passing low pressure air through a porous membrane in which the particles are maintained in combination with a vibratory action. A suitable electrostatic printing screen 56 is mounted within the screen retaining frame 54 and the screen retaining frame 54 is then secured to the screen support frame 32 by means of the bolts 55. The mandrels 101 mounted on each of the mandrel shafts 97 are sized to accommodate containers C which are then loaded into a suitable delivery mechanism for delivery to the container dispensing mechanism 126.

Upon energization of the electric motor 17, the drive belt trained around the pulleys 19, 20 will drive the main drive shaft 14 which will, in turn, through the roller chain 26 drive the screen drive shaft 21. Rotation of the drive shaft 21 will cause the friction wheel 34 to rotate. At the start of a printing cycle, the screen support frame 32 is located in its lowermost position, that is the position as shown in FIGURE 1 where a mandrel 101 is positioned in horizontal alignment with the upper margin of the electrostatic printing screen 56.

At the start of a complete printing cycle, where a mandrel 101 is located at the container dispensing mechanism 126, a complete printing cycle will be performed when the mandrel 101 rotates through a 360° revolution and again arrives at the container dispensing mechanism 126. In this position, the mandrel 101 is located at the "loading station" S₁ and actuation of the container dispensing mechanism 126 will deposit a single container C on the mandrel 101.

The rotation of the transversely extending drive shaft 14 will rotate the pinion gear 66 which will, in turn, rotate the pinion gear 65 and the primary Geneva shaft 63. Rotation of the primary Geneva shaft 63 will cause the pinwheel 69 to rotate in a counter-clockwise direction, reference being made to FIGURE 4. As this occurs, the annular side wall of the pin-wheel 69 will be slightly spaced from the concave guide surfaces 81 of the slot-wheel 77. Moreover, the outwardly extending actuator pin 71 will become engaged through the slot 80 in the slot-wheel 77 substantially as shown in FIGURE 4. As this occurs, the continued rotation of the pin-wheel 69 will cause the slot-wheel 77 to rotate in a clockwise direction, reference being made to FIGURE 4 until the slot 80, which is engaged by the pin 71 is shifted 90° to its lowermost position as shown in FIGURE 4. Rotation of the slot-wheel 77 will cause the drive chain 90 to rotate the sprocket 87 through a 45° movement. It can thus be seen that the pin-wheel 69 will rotate for approximately 270° during the time in which the slot wheel remains in a stationary position. As the pin-wheel 69 again reaches the next adjacent slot 80 in the position as shown in FIGURE 4, the pin 71 will become engaged in the slot 80 causing the slot-wheel 77 to rotate an additional 90° in the manner as previously described. Rotation of the slot-wheel for this additional 90° will cause the drive chain 90 to rotate the sprocket 87 through an additional 45° movement. Accordingly, it can be seen that rotation of the slot-wheel through 180° has rotated the valve drum 83 and the turret 92 carrying the mandrel 101 through a 90° arc. This 90° movement has positioned the mandrel 101 at the second work station or printing station S₂ where the mandrel is moved to the printing position.

When a container C is forced onto the mandrel 101, the valve drum 83 will be in the position as indicated in FIGURE 5. In other words, all of the radial fluid ducts 116, with the exception of the fluid duct immediately to the left of the mandrel 101 located in the loading station S₁ will be in communication with the primary air passage 111 and, therefore, maintained under vacuum. Thus, the vacuum is imposed upon the mandrel 101 which urges the container C onto the mandrel 101. Moreover, the fingers 108 will engage the bottom wall of the container C preventing collapsing of the bottom wall. Rotation of the screen drive shaft 21 will cause the peripheral gear surface 35 of the friction wheel 34 to engage the flange 36 on the screen support frame 32. Rotation of the shaft 21 in the clockwise direction will rotate the friction wheel 34 in the clockwise direction creating an upwardly directed force on the flange 36 and thereby causing the screen support frame to pivot upwardly about the screen support shaft 30. The gear surface 35 will remain in contact with the flange 36 until the screen support frame 32 reaches its uppermost position or upper limit of movement. The friction wheel 34 is designed with a proper size so that the gear surface 35 will remain in contact with the flange 36 until this upper limit of movement is achieved. At this point, the gear surface 35 will move out of contact with the flange 36 and the flat 37 will become aligned with the flange 36. Removal of the upwardly directed force on the screen support frame 32 permits the screen support frame 32 to be shifted to its lower position.

The pneumatic drive mechanism 46 will shift the screen support frame 32 to its lower or initial position after the screen support frame 32 has reached its uppermost posi-

tion. The timing of the operation of the pneumatic drive mechanism 46 with the rotation of the friction wheel 34 can be performed by any conventional control mechanism. The pneumatic drive mechanism is desirable for a means to move the screen support frame 32 to its lower position since the screen support frame 32 will not suffer a sudden shock or jar as it reaches the lower position. Moreover, as the screen support frame 32 reaches its lowermost position, it will strike the bumper pad 44 which will cushion the stopping movement of the screen support frame 32. The mandrel 101 is continually rotated with the mandrel shaft 97 as the bevel gears 98 on the base of the mandrel shafts 97 are in continued meshing engagement with the continuously rotating spiral gear 99. The bevel gear 98 is sized so that it provides the proper peripheral speed for the mandrel 101 according to the speed of movement of the screen support frame 32. In this manner, tangential departure and approach between the mandrel 101 and the electrostatic printing screen 56 is maintained. The ink feeding mechanism 58 is so positioned so that the discharge nozzle 61 is positioned at this tangential line of closest approach. Consequently, electroscopic ink will be delivered to the electrostatic printing screen at this tangential line of closest approach, where the particles are then captured in the electrostatic field. The ink particles will pass through the open mesh portions of the electrostatic printing screen 56 and in this manner will project the image on the electrostatic printing screen 56 to the container C.

Continued rotation of the main drive shaft 14 will continue to cause the pin-wheel 69 to rotate the slot-wheel 77 of the secondary Geneva mechanism 76 through continuous 90° movements. Rotation of two 90° movements will rotate the turret 92 through two successive 45° movements where the mandrel 101 is introduced into the fixing tank 127. In this manner, the container C is then introduced into the vapor phase of the solvent in the fixing tank 127 and the electrostatic printing image is fixed in the manner as previously described. Two successive 90° movements of the secondary Geneva mechanism 76 will move the turret 92 through two successive 45° movements until the turret has progressed through a 270° arc. In these last two 45° positions, the mandrel 101, with the container C disposed thereon has been moved out of the fixing tank 127, thereby permitting the solvent contained in the electroscopic ink to evaporate. It is to be noted that during the portion of the time that the mandrel 101 was moved through the first 270° arc, the radial fluid duct 116 associated with that mandrel 101 has been in continual fluid communication with the primary air passage 111, thereby maintaining the mandrel 101 under a vacuum. However, as the turret 92 rotates through another 45° movement, the radially extending fluid duct 116 associated with the mandrel 101 will be moved out of contact with the primary air passage 111. As the mandrel reaches a position where it is 315° from its initial starting position, it is moved into communication with the secondary air line 114. Accordingly, air under pressure is supplied to the radial fluid duct 116, and the axial fluid duct 117 and to the mandrel 101 in the manner previously described. The container C disposed on the mandrel 101 will thereupon become ejected from the mandrel 101 and deposited in the discharge tube 125. The air exhaust from the mandrel 101 will also assist in forcing each container C into the discharge tube 125 and thereby serve as an assist to the vacuum maintained on the tube 125.

Continued rotation of the turret 92 will move the mandrel 101 to its initial starting position or to the loading station S₁ where a printing cycle has been completed. However, it can be recognized that during the time that one of the mandrels 101 is progressed through each of the five work stations, the other seven mandrels 101 on the turret 92 also progresses through the same five work stations in similar manner. Thus after the mandrel 101 is again positioned at the container dispensing mechanism

126, a new cycle can then be initiated in the manner as described.

Detailed description of apparatus B

It is possible to provide a modified form of electrostatic printing apparatus B substantially as shown in FIGURES 14-18, and which is substantially similar in its operation to the previously described electrostatic printing apparatus A. The electrostatic printing apparatus B generally comprises a supporting frame 150 which includes a pair of spaced longitudinally extending base channels 151 connected at their corners with uprights 152. The uprights 152 are connected by a pair of upwardly spaced longitudinally extending support channels 153. The upper channels 153 and the base channels 151 are connected by transverse channels 154. Extending between each of the transverse channels 154 and being spaced between the longitudinally extending support channels 153 are a pair of transversely spaced longitudinally extending intermediate support channels 155, 156. Extending between the forward support channel 153 and the intermediate support channel 155 are a pair of longitudinally spaced crossbars 157 and similarly extending between and welded to the rear support channel 153 and the intermediate support channel 156 are a pair of longitudinally spaced crossbars 158. The components of the supporting frame 150 may be formed of any suitable rolled shape of channel, such as an I-beam shape, an H-beam shape, a standard U-beam shape or an L-beam shape as illustrated.

Bolted or otherwise rigidly secured to the upper surface of the longitudinally extending supporting channels 153 and to each of the intermediate support channels 155, 156 are four transversely aligned pillow blocks 159, 160, 161 and 162, and journaled therein is a transversely extending drive shaft 163, substantially as shown in FIGURE 14. The drive shaft 163 is held in transverse alignment within the respective pillow blocks by means of conventional washers and lock rings 164 mounted on each side of the respective pillow blocks. Bolted or otherwise rigidly secured to the forwardly presented support channel 153 is a variable speed electric motor 165, which is preferably of the explosion-proof type. The motor is connected through a speed reducer 166 to a V-belt pulley 167 and which rotates a matching V-belt pulley 168 on the drive shaft 163 through a V-belt 169. The electric motor 165 and the speed reducer 166 are conventional in their construction and the main drive shaft 163 is driven through energization of the electric motor 165.

Extending longitudinally between the crossbars 157 and journaled in pillow blocks 170, which are bolted to the upper surfaces of the cross bars 157 is a rotatable shaft 171. A bevel gear 172 mounted on the left-hand end of the shaft 171, reference being made to FIGURE 14 meshes with a mating bevel gear 173, mounted on the main drive shaft 163. Bolted or otherwise rigidly secured to the upper surface of the forwardly presented support channel 153 and the intermediate support channel 155 are a pair of transversely aligned pillow blocks 174 and extending between and journaling the pillow blocks 174 is a screen drive shaft 175. Fixedly mounted on the screen drive shaft 175 is a bevel gear 176, which is positioned in meshing engagement with a matching bevel gear 177 on the right-hand end of the rotatable shaft 171. Thus through the meshing engagement of the bevel gears 176, 177, the screen drive shaft 175 is directly rotatable through the rotatable shaft 171.

Similarly bolted or otherwise secured to the upper surfaces of the crossbars 158 are a pair of longitudinally aligned pillow blocks 178 and extending between and journaled in the pillow blocks 178 is a rotatable shaft 179. Mounted on the left-hand end of the shaft 179, reference being made to FIGURE 14 is a bevel gear 180, which is positioned in meshing engagement with a matching bevel gear 181, the latter being in turn mounted on the drive shaft 163. Thus, it is possible to rotate the

rotatable shaft 179 through the meshing engagement of the bevel gears 180, 181. Also bolted or otherwise rigidly secured to the upper surfaces of the rearwardly spaced support channel 153 and the intermediate support channel 156 are a pair of pillow blocks 182 for rotatably supporting a screen drive shaft 183. The screen drive shaft 183 is driven by means of a bevel gear 184 mounted thereon and which is positioned in meshing engagement with a matching bevel gear 185 mounted on the right-hand end of the rotatable shaft 179, substantially as shown in FIGURE 14. The rotatable shafts 171, 179 and the screen drive shafts 175, 183 are held in alignment within the respective pillow blocks in which they are journaled by means of washers and lock rings 186 mounted on each side of each of the respective pillow blocks. Each of the bevel gears 172, 173, 176, 177, and 180, 181, 184 and 185 is conventionally provided with hubs 187. The hubs 187 may be keyed to or secured to the respective shafts on which the bevel gears are mounted by means of set screws (not shown).

Welded or otherwise secured to the right transverse channel 154, reference being made to FIGURE 14 are a pair of upstanding brackets 188 which form an elongated vertical support plate 189. Bolted to the interiorly presented surface of the vertical support plate 189 are two transversely spaced pairs of transversely aligned pillow blocks 190, 191. Extending between the pillow blocks 190 and being journaled therein is a screen support shaft 192 and similarly extending between the pillow blocks 191 and being journaled therein is a screen support shaft 193. Each of the screen support shafts 192, 193 is pivotal within its respective pillow block and retained by means of conventional washers and locking rings 194 mounted on each side of each of the respective pillow blocks in which the shafts are journaled. Mounted on the screen support shaft 192 is an oscillating screen support frame 195 having an enlarged hub 196 which is concentrically disposed about the shaft 192 and keyed thereto. Also mounted on the shaft 193 is an oscillating screen support frame 197 having an enlarged hub 198, which is concentrically disposed about the shaft 193 and keyed thereto. The screen support frame 197 is shiftable between upper and lower limits and a shifting movement from a lower position to an upper position, and back to a lower position constitutes one screen cycle. The screen support frame 195 is also shiftable between upper and lower limits and a shifting movement from an upper position to a lower position, and back to an upper position constitutes one printing cycle. In other words, each of the screen support frames 195, 197 moves in opposite directions and in timed relationship to each other.

Rigidly mounted on the interior ends of each of the screen drive shafts 183, 175 are heat-shaped cams or so-called "covered heart" cams 199, 200 respectively. Each of the cams 199, 200 is integrally provided with hubs 201 which are concentrically disposed about the ends of the shafts 175, 183 and are secured thereto by means of Woodruff keys 202. The cams 199, 200 are more fully illustrated in FIGURES 16 and 17 and each have an identical shape so that the screen support frames 195, 197 will have substantially identical projectories but in opposite directions in a manner to be hereinafter described in more detail. However, by reference to FIGURE 14, it can be seen that the cams 199, 200 are oppositely disposed and are 180° out of phase with each other to produce correspondingly reciprocal actions.

Each of the cams 199, 200 is provided with internal heart-shaped camming grooves 203 which are sized for accommodating rollers 204 mounted on the exteriorly presented faces of each of the screen support frames 195, 197. The rollers 204 are mounted on stub shafts 205 secured to the exterior faces of each of the frames 195, 197 and are journaled thereon by means of roller bearings 206. Thus, as the screen drive shafts 175, 183 rotate, the rollers 204 which serve as "cam followers" will

ride in the camming grooves 203 of the respective cams 199, 200. These camming grooves 203 are designed to provided the oscillating upper and lower shifting movements of each of the screen support frames 195, 197. By reference to FIGURE 17, which presents an end elevational view of the cam 199, the cam rotates in a counter-clockwise direction. This, in effect, causes the cam follower or roller 204 to move in a clockwise direction. Accordingly, when the roller 204 moves upwardly in the camming groove 203 from the line designated x in FIGURE 16, to the line designated y, the screen support frame 197 will shift downwardly. When the roller 204 moves through the same trajectory in the cam 199, the screen support frame 195 will shift downwardly. The movement of the cam follower 204 through the remainder of the camming groove 203 causes the screens to move to their initial starting positions.

Each of the screen support frames 195, 197 is provided with inwardly extending spaced opposed mounting blocks 207 and secured thereto by means of bolts 208 are screen retaining frames 209, 210. The screen retaining frames 209, 210 are designed to retain electrostatic printing screens 211, 212. Each of the frames 209, 210 is designed so that the electrostatic printing screens 211, 212 may be easily removed and inserted therein when it is desired to change the printing design. Furthermore by reference to FIGURE 15, it can be seen that the screen retaining frames 209, 210 are arcuately shaped and have an arcuate distance of approximately 45° with respect to the screen support shafts 192, 193. The electrostatic printing screens 211, 212 are substantially similar to the previously described electrostatic printing screen 56 and may be constructed in similar manner. The electrostatic printing screens 211, 212 are generally formed of a fine mesh conductive material having masked non-printing areas and non-masked printing areas. The non-masked portions or printing areas of the screens 211, 212 are designed to permit pigments in the forms of the ink powders to pass through the interstices of the open areas. It should be recognized that the two printing screens 211, 212 do not necessarily have to be provided with the same type of printed image or design. However, if each is provided with a similar design and which are positioned so that marginal registration is achieved when an article is printed between the two screens, it is possible to employ multicolor electrostatic printing.

Air operated ink feeding mechanisms similar to the previously described ink feeding mechanism 58 are mounted in close proximity to each of the electrostatic printing screens 211, 212. These air operated ink feeding mechanisms have not been illustrated in connection with the electrostatic printing apparatus B, in order to provide clarity in the drawings. However, it should be recognized that they can be suitably mounted on the supporting frame 150 in any conventional manner. Moreover, the ink feeding mechanisms are so positioned so that the discharge nozzles forming part of the ink feeding mechanism are in close proximity to the screens substantially as shown in FIGURE 18. Again, the discharge nozzle is designed to have a relatively small height and a width substantially equal to the width of the electrostatic printing screens 211, 212. It is again desirable to adjust the air gap between the terminal ends of the discharge nozzle and the surface of the electrostatic printing screens 211, 212 to a distance of about 0.005" to 0.12". Similarly, the belt operated ink feeding mechanism previously described could be used with the apparatus B.

Operatively mounted on the main drive shaft 163 is a four position turret 213 having four radially spaced outwardly extending mandrel shafts 214. The turret 213 is driven by a Geneva type mechanism 215 substantially as shown in FIGURE 15 and which is substantially similar to the Geneva type actuating mechanism described in our copending application Serial No. 482,475, filed Aug.

5, 1965. Operatively mounted beneath the main drive shaft 163 in conventional bearing blocks (not shown) is a primary Geneva shaft 216 which is continuously rotatable and may be driven through pinion gears (not shown) mounted on the main drive shaft 163 and on the primary Geneva shaft 216. Mounted on the primary Geneva shaft 216 is a primary Geneva mechanism 217 which generally comprises a pin-wheel or so-called "pin-gear" 218. The pin-wheel 218 is generally circular in cross section and is provided with an outwardly extending lobe 219 and mounted on the lobe 219 is an axially extending actuator pin 220. By reference to FIGURE 15, it can be seen that the lobe is somewhat triangularly shaped and extends beyond the line which would form the peripheral margin of a truly circular wheel. The pin-wheel 218 is also provided in the area of the lobe 219 with a quarter-round or arcuate recess 221 having an arcuate guide wall 222.

Rotatably mounted on the main drive shaft 163 which also serves as a secondary Geneva shaft is a secondary Geneva mechanism 223 which generally comprises a slot-wheel or so-called "star-wheel" 224. The slot-wheel 224 is provided with four radially spaced crowns 225 connected by arcuately shaped webs 226. Thus, by reference to FIGURE 15, it can be seen that each of the crowns 225 is spaced at 90° intervals and is connected by the arcuately shaped webs 226. The radius of curvature of the arcuately shaped webs 226 is substantially equal to the radius of the pin-wheel 218. Furthermore, the arcuately shaped webs 226 are provided with concave guide surfaces 227. Each of the crowns 225 is provided with relatively deep pin-engaging slots 228 which are sized to accommodate the actuator pin 220. By reference to FIGURE 15, it can be seen that the slots 228 are sufficiently deep so that the actuator pin 220 is extended therein to the full length of the guide slot 228 when the crowns 225 of the slot-wheel 224 are engaged with the guide wall 222 of the pin-wheel 218.

40 A web-wheel (not shown) and a valve drum (also not shown) are connected to and rotatable with the secondary Geneva mechanism 223 in the manner as described in our copending application Serial No. 482,475, filed Aug. 25, 1965. The valve drum in said copending application is similar to the valve drum 83 in the electrostatic printing apparatus A and is similarly provided with four radial fluid ducts and four communicating axial fluid ducts. However inasmuch as this construction and operation is described in the aforesaid copending application, it is neither illustrated nor described in detail herein. 45 It can be seen that the mandrel shafts 214 extend outwardly at points midway between each of two crowns 225 so that the turret 213 is rotated approximately 45° with respect to the slot-wheel 224. The valve drum, which is connected to the slot-wheel 224 is rotatable in a valve manifold 229, which is in turn secured to brackets 230. The brackets 230 are welded or otherwise rigidly secured to the intermediate support channel 155 in the manner as shown in FIGURE 14. It can also be seen by reference to FIGURE 15 that the secondary Geneva mechanism 223, in effect, forms a quill on the main drive shaft 163 and is rotatable with respect to the drive shaft 163.

50 Rotation of the main drive shaft will cause the primary Geneva shaft 216 to rotate in a counter-clockwise direction, reference being made to FIGURE 15. This will, in turn, cause the pin-wheel 218 to rotate in a counter-clockwise direction. As this occurs, the annular side wall of the pin-wheel 218 will be slightly spaced from the concave guide surfaces 227 in one quadrant. Inasmuch as the guide surface 227 has the same radius of curvature as the annular surface of the pin-wheel 218, the secondary Geneva mechanism 223 will not rotate on the main drive shaft 163. Continued rotation of the pin-wheel 218 will cause the outwardly extending pin 220 to engage a slot 228 in the slot-wheel 224. As the pin-wheel 218 rotates, 55 it will rotate the slot-wheel 224 in a clockwise direction

for a 90° movement. It can be seen that the pin-wheel 218 will rotate the slot-wheel 224 in a clockwise direction for 90° and thereafter the pin-wheel 218 will rotate for approximately 270° during which time the slot-wheel 224 remains in a stationary position on the drive shaft 163.

It can be seen that the mandrel shafts 214 are also hollow and communicate with container supporting mandrels 231 rotatably mounted on the outer ends thereof. Thus, as the secondary Geneva mechanism 223 rotates, it will rotate the valve drum in the manner as shown in connection with the electrostatic printing apparatus A and create conditions of positive or reduced pressure on the mandrels 231 according to the position of the secondary Geneva mechanism 223.

The mandrel 231 is more fully illustrated in FIGURE 18 and is generally formed of a frusto-conical shape having an annular tapering side wall 232. The mandrel 231 is also provided with a relatively flat centrally apertured end wall 233 and a somewhat concave end wall 234. The mandrel 231 is hollow thereby providing an axial interior chamber 235, which is also formed with a relatively flat interior shoulder 236 for retaining a roller bearing 237. Axially spaced from the bearing 237 is a second roller bearing 238 which in turn is retained in position by means of a locking ring 239. Each of the bearings 237, 238 is held in axial alignment by means of diametrically enlarged shoulders formed on the mandrel shaft 214 and which abut against the left hand margins of each of the bearings 237, 238, substantially as shown in FIGURE 18.

At its outer end, the mandrel shaft 214 is reduced and is integrally provided with a cup engaging open ended extension 240 having cup engaging fingers 240', for engaging the bottom wall of the container C which may be disposed thereon. The cup engaging fingers 240' are designed to engage the bottom wall of the container C in order to prevent collapsing of the container bottom wall when a vacuum is applied to the mandrel shaft 214 and to the mandrel 231.

The container supporting mandrel 231 is designed to accommodate disposable, nestable, thin-walled plastic containers such as the type used in the electrostatic printing apparatus A. Again, the mandrel 231 is adapted for easy removal and replacement with a similar mandrel that is designed to accommodate different types of open-ended containers. Moreover, by reference to FIGURE 18, it can be seen that the mandrel 231 is positioned between the discharge nozzles of each of the two feeding mechanisms (not shown) so that the container C disposed on the mandrel 231 may be simultaneously printed as each of the screen support frames 195, 197 move in pretimed relationship.

Rigidly secured to the rearward end of the mandrel 231 is a friction wheel 241 which resides in meshing engagement with a friction drive wheel 242, the latter being rigidly secured to the main drive shaft 163 and rotatable therewith. Therefore, as the main drive shaft rotates, it will rotate the friction drive wheel 242 and hence the friction wheels 241 connected to the mandrel 231. This type of action will rotate the mandrel 231 in timed relationship to the oscillating screen frames 195, 197. Thus, it can be seen that the annular side wall 232 of the container is located so that it parallels the surface of the electrostatic printing screens 211, 212. The container C disposed on the mandrel 231 is so positioned in an axis of rotation so that the exterior wall thereof tangentially approaches and departs from the electrostatic printing screens 211, 212. Thus, printing will occur along these two elemental lines of closest approach between the container C and each of the electrostatic printing screens 211, 212. Moreover, the mandrel 231, with the container C supported thereon is rotated at approximately the same rate of speed as the movement of the screen support frames 195, 197 so that a continuing line of tangency occurs between the surfaces of each of the screens 211, 212 and

the container C supported on the mandrel 231. Simultaneously with the rotation of the mandrel 231 with the container C supported thereon, ink is distributed from the feeding mechanisms through the electrostatic printing screens 211, 212 so that an image is formed on the side wall of the container C.

The electrostatic printing apparatus B also includes a container dispensing mechanism 243 for intermittently dispensing or depositing the containers C on each of the mandrels 231 as they pass the container dispensing mechanism 243. The container dispensing mechanism 243 is vertically positioned and is disposed above the mandrel 231 as it reaches its uppermost position, reference being made to FIGURE 15. Again, a simple control circuit (not shown) may be provided for actuating the solenoid on the container dispensing mechanism 243 pursuant to a positioning of the mandrel 231 in alignment with the dispensing mechanism 243.

A discharge tube 244 is mounted in a position which corresponds to a 270° rotation of the turret 213 from the cup dispensing mechanism 243. As the mandrel 231 becomes aligned with the discharge tube 244, the valve drum associated with the secondary Geneva mechanism 223 will become positioned so that a positive air pressure is applied to the mandrel 231 causing the container C thereon to become ejected and deposited in the discharge tube 244. Furthermore, the discharge tube 244 is connected to a suitable air exhaust system (not shown) thereby aiding in the removal of the containers C after the printing operation.

An ink fixing tank 245 is also mounted on the frame 150 and is disposed between the two lower longitudinal base channels 151 in the manner as shown in FIGURE 15. The ink fixing tank 245 has an arcuate bottom wall 246, which somewhat approximates the arcuate movement of the mandrel 231. This type of association is more fully shown in FIGURE 15. The method of fixing the electrostatic printing image is the same as used in electrostatic printing apparatus A and is, therefore, not described in detail herein.

By reference to FIGURE 15, it can be seen that the electrostatic printing apparatus B is so constituted and arranged that there are, in effect, four work stations which are located in a 360° circle, namely the arcuate movement of at least one mandrel 231 in a full cycle. It can be seen that each of the mandrels 231 rotates in a clockwise direction, reference being made to FIGURE 15 and that each printing cycle actually starts at the point where the mandrel 231 is in vertical alignment with the container dispensing mechanism 243. Thus, the dispensing of a container C on a mandrel 231, which is located at the container dispensing mechanism 243, constitutes a first work station or so-called "loading station" S₁. As mandrel 231 with the container C supported thereon moves in a clockwise direction to the screen supporting frame, 195, 197, it is moved into a printing position for receiving a desired imprinted image. The printing of the container C constitutes a second work station or so-called "printing station" S₂, which is located at a distance of 90° from the loading station S₁. After the container has received the electrostatic image at the printing station S₂, it is transferred to a fixing station S₃ which constitutes a third work station. After the fixing station S₃, the mandrel is rotated until it is aligned with a discharge station S₄ which comprises the discharge tube 244. During the time that the mandrel 231 is removed from the fixing tank 245 and until it becomes aligned with the tube 244, sufficient time is provided for solvent evaporation from the image permitting the image to air dry. It is to be recognized that an electrostatic field is maintained between the electrostatic printing screen 211, 212 and the mandrel 231 in the same manner that an electrostatic field was maintained in the electrostatic printing apparatus A.

Operation of the apparatus B

In use, the electrostatic printing apparatus B is somewhat similar in its operation to the electrostatic printing apparatus A. Upon energization of the electric motor 165, the drive belt 169 trained around the pulleys 167, 168 will drive the main drive shaft 163 which will, in turn, drive the screen drive shafts 175, 183.

At the start of a complete printing cycle, the mandrel 231 is located at the container dispensing mechanism 243. A complete printing cycle will be performed when the mandrel 231 rotates through a complete 360° revolution and again arrives at the container dispensing mechanism 243. In this position, the mandrel 231 is located at the loading station S₁ and actuation of the container dispensing mechanism 243 will deposit a single container C on the mandrel 231. Rotation of the transversely extending drive shaft 163 will rotate the primary Geneva shaft 216 and the primary Geneva mechanism 217 in the manner as previously described. Rotation of the pin-wheel 218 will cause a pin 220 to become engaged in a slot 228 of the slot-wheel 224. As this occurs, the slot-wheel 224 will rotate through a 90° revolution in a clockwise direction, reference being made to FIGURE 15 until the mandrel 231 is positioned at the second work station or printing station S₂. It is to be recognized that during the time that the mandrel 231 is positioned at the loading station S₁ and until it arrives at the discharge station S₄, the mandrel 231 is maintained under a vacuum causing the container C to be retained thereon.

At the start of the printing cycle, the screen support frame 195 is located at its uppermost position and the screen support frame 197 is located at its lowermost position, substantially as shown in FIGURE 15. Rotation of the screen drive shafts 175, 183 will cause the cams 199, 200 to rotate. As this occurs, the cam follower 204 will move in the camming grooves 203 of the respective cams 199, 200. Movement of the cam follower 204 in the grooves 203 will cause the screen support frame 197 to shift upwardly and the screen support frame 195 to shift downwardly. As this occurs, the mandrel 231 is rotated during the time that the two screen support frames 195, 197 are shifting with respect to the mandrel 231. Accordingly, a continuing line of tangency is maintained between the surface of the mandrel 231 with the container C supported thereon and the surfaces of each of the electrostatic printing screens 211, 212. As ink passes through the electrostatic printing screens 211, 212, the image on the surface of the screens will thereupon be transferred to the container C. The cam follower 204 moves in the camming groove 203 from the position x to the position y designated in FIGURE 16 to cause the above described movement of the screen support frames 195, 197.

Continued rotation of the main drive shaft 163 will continue to cause the pin-wheel 218 to rotate and thereby rotate the slot-wheel 224 through continuous 90° movements. As this occurs, the mandrel 231 will be shifted from the printing position to the fixing station S₃ where it is introduced into the fixing tank 245. However as the primary Geneva mechanism 217 is rotated through a 270° movement, where no movement of the secondary Geneva mechanism 223 takes place, the cam follower 204 will move in a clockwise direction, reference being made to FIGURE 16 from the position y thereof through a 270° movement to the position x. A successive 90° movement of the secondary Geneva mechanism 223 will move the turret 213 90° until the mandrel 231 is located in alignment with the discharge tube 244. At this position, the vacuum previously maintained on the mandrel 231 will be discontinued and the mandrel 231 will be subjected to a positive pressure in the same manner as in the electrostatic printing apparatus A. This will, in turn, cause the container C on the mandrel 231 to be ejected and deposited in the discharge tube 244.

Continued rotation of the turret 213 will move the mandrel 231 to its initial starting position or loading station S₁ where a printing cycle has been completed. However, it can be recognized that during the time that 5 one of the mandrels 231 is progressed through each of the four work stations, the other three mandrels 231 on the turret 213 also progress through the same four work stations in similar manner. Thus after the mandrel 231 is again positioned at the container dispensing mechanism 243, a new cycle can be initiated in the manner as described.

Detailed description of apparatus D

It is possible to provide another modified form of electrostatic printing apparatus D substantially as shown in FIGURE 19 and which is substantially similar in its operation to the previously described electrostatic printing apparatus B. The electrostatic printing apparatus D generally comprises a supporting frame 300 which includes a 15 pair of spaced upper longitudinally extending channels 301. The electrostatic printing apparatus D is similarly provided with base channels and uprights (not shown) for supportive engagement with the upper channels 301 as in the case of the electrostatic printing apparatus B. 20 The electrostatic printing apparatus D also includes transverse channels 302 and a pair of spaced longitudinally extending intermediate support channels 303. Crossbars 303' are welded to and extend between the channels 301 and the intermediate support channels 303. A pair of 25 transversely spaced stainless steel support plates 304 are supported on and welded to the upper surfaces of the transverse channels 302, the longitudinally extending support channels 301 and the intermediate support channels 303 in the manner as shown in FIGURE 19. The remainder of the supporting frame 300 is substantially identical to the previously described supporting frame 159 of the electrostatic printing apparatus B and is, therefore, neither illustrated nor described in further detail herein. 30 However, it is pointed out that components of the supporting frame 300 may be formed of any suitable roll shape of channel, such as an I-beam shape, an H-beam shape, a standard U-beam shape or an L-beam shape, as illustrated.

The electrostatic printing apparatus D is also provided 35 with an electric motor 165, operatively mounted on the supporting frame 300 and which, in turn, drives a turret 213 with mandrel support shafts 214 and four radially spaced mandrels 231. The turret 213 is similarly driven through a Geneva type actuating mechanism substantially 40 identical to the mechanism described in connection with the electrostatic printing apparatus B. The electric motor 165 is similarly designed to operate rotatable shafts 305 which are journaled in pillow blocks 306, the latter being bolted to the upper surface of the support frame 300 in 45 the manner illustrated in FIGURE 19. The rotatable shafts 305, which are transversely spaced on opposite longitudinal sides of the support plate 304 are provided with universal joints 307 at each of the right-hand ends. The universal joints 307 are conventional in their 50 construction and are, therefore, not described in further detail herein. Angularly disposed stub shafts 308 are secured to the universal joints 307 in the manner as shown in FIGURE 19 and are journaled in pillow blocks 309 which are secured to the support plates 304 by means of 55 bolts 309'.

Fixedly mounted on the stub shafts 308 are bevel gears 310 which are positioned in meshing engagement with bevel gears 311, the latter being mounted on screen drive shafts 312. The screen drive shafts 312 are journaled 60 in pillow blocks 313, the latter being bolted to the upper surface of the support plate 304 by means of bolts 313'. Secured to the outer ends of each of the screen drive shafts 312 are cams 314, 315 which are substantially identical to the previously described cams 199, 200, respectively. Again, the cams 314, 315 are oppositely dis-

posed and are 190° out of phase with each other to produce correspondingly reciprocal actions.

Welded or otherwise rigidly secured to the right transverse end of the support plate 304 are two pairs of upstanding brackets 316, 317 which form elongated vertical support plates 318, 319. Bolted to the interiorly presented surfaces of each of the vertical support plates 318, 319 are two transversely spaced pairs of pillow blocks 320, 321 and journaled in each of the pillow blocks 320, 321 are screened support shafts 322, 323, respectively. By reference to FIGURE 19, it can be seen that the brackets 316, 317 are so arranged so that the screen support shafts 322, 323 are perpendicular to the side wall of the mandrels and rather than being perpendicular to the axial centerline of the mandrel. Each of the screen support shafts 322, 323 is pivotal within the respective pillow blocks and retained by means of conventional washers and locking rings 324 mounted on each side of the respective pillow blocks in which the shafts are journaled.

Mounted on the screen support shaft 322 is an oscillating screen support frame 325 having an enlarged hub 326, which is concentrically disposed about the shaft 322 and keyed thereto. Also mounted on the shaft 323 is an oscillating screen support frame 327 having an enlarged hub 328 which is concentrically disposed about the shaft 323 and keyed thereto. The screen support frame 327 is shiftable between upper and lower limits and a shifting movement from a lower position to an upper position and back to a lower position constitutes one screen cycle. The screen support frame 325 is also shiftable between upper and lower limits and a shifting movement from an upper position to a lower position and back to an upper position also constitutes one printing cycle. Thus, the screen support frames move in opposite directions and in timed relationship to each other.

Each of the cams 314, 315 is provided with internal heart-shaped camming grooves (not shown) which are sized for accommodating rollers (also not shown) mounted on the exteriorly presented faces of each of the screen support frames 325, 327. Thus as the screen drive shafts 312 rotate, the rollers which serve as "cam followers" will ride in the camming grooves of the respective cams 314, 315 and provide an oscillating upper and lower shifting movements of each of the screen support frames 325, 327. The remainder of the action for moving the screen support frames 325, 327 is similar to the operation of moving the screen support frames 195, 197 and is, therefore, not described in further detail herein. Similarly, each of the screen support frames 325, 327 is provided with electrostatic printing screens. However, it can be seen that the electrostatic printing screens are mounted in screen retaining frames 328' which are, in turn, secured to the screen support frames 327, by means of spacer blocks 329. Moreover, the screen retaining frames 328' are parallel to and constitute extensions of the screen retaining frames 325, 327. Thus, the electrostatic printing screens are also parallel to and spaced slightly from the side walls of the mandrel.

By employing an electrostatic printing screen support frame which oscillates about an axis which is perpendicular to the axis of rotation of the mandrel, it is not necessary to employ a curvilinear screen. Consequently, a flat electrostatic printing screen is employed in this embodiment.

Operation of the apparatus D

In use, the electrostatic printing apparatus D is substantially similar in its operation to the electrostatic printing apparatus B. Upon energization of the electric motor 165, the turret will rotate the mandrels by means of the Geneva type drive mechanism. Moreover, the energization of the motor will rotate the shafts 305. It can be seen that the screen drive shafts 312 will rotate therewith and thereby oscillate the screen support frames 325, 327 in timed relationship. This action is permitted by means of the universal joints 307.

The remainder of the operation of the electrostatic printing apparatus D is substantially identical to the operation of the previously described electrostatic printing apparatus B. It is to be noted, however, that the flat electrostatic printing screen can be used to maintain the tangential approach and departure between the mandrel or the article retained thereon and the electrostatic printing screen. This type of relationship can be achieved with the flat screen inasmuch as the axis of movement of the flat screen is perpendicular in space to the side wall of the mandrel or the side wall of the container being printed, which is disposed on the mandrel.

It should be understood that changes and modifications in the form, construction, arrangement and combination of parts presently described and pointed out may be made and substituted for those herein shown without departing from the nature and principle of our invention.

Having thus described our invention, what we desire to claim and secure by Letters Patent is:

1. An electrostatic printing apparatus comprising:
  - (a) base means,
  - (b) a first continuously rotatable shaft operatively mounted on said base means,
  - (c) an actuating wheel operatively mounted on said shaft and rotating through continuous 360° revolutions,
  - (d) a second shaft operatively disposed in spaced relation to said first shaft,
  - (e) a slot-wheel having a plurality of engageable slots operatively mounted on said second shaft and being intermittently rotatable,
  - (f) an extended pin on said actuating wheel for engaging any of said slots on said slot-wheel and rotating the slot-wheel through 90° arcs during 90° arcuate rotational movements of said actuating wheel,
  - (g) a turret operatively connected to said slot-wheel and being rotatable therewith so that said turret is moved to successive positions which are spaced 45° apart,
  - (h) a plurality of article retaining means mounted on said turret and being sized to retain desired articles for printing,
  - (i) an oscillating screen frame operatively mounted on said base means and being shiftable between upper and lower positions during a printing cycle,
  - (j) an electrostatic printing screen operatively associated with said screen frame and being movable therewith,
  - (k) means for feeding a supply of electroscopic ink to said screen when said article retaining means are aligned with said screen,
  - (l) means for moving said movable screen frame in pretimed relationship to said turret so that each one of said article retaining means becomes aligned with said screen,
  - (m) and means for creating an electrostatic field between said screen and article retaining means so that ink will pass through the open portions of the screen to the article retaining means.
2. An electrostatic printing apparatus comprising:
  - (a) base means,
  - (b) a movable screen frame operatively mounted on said base means and being shiftable between upper and lower positions during a printing cycle,
  - (c) an electrostatic printing screen operatively associated with said screen frame and being movable therewith,
  - (d) driving roller means operatively mounted on said base means and having an arcuate portion and a flat portion, said arcuate portion being engageable with said screen frame for moving said screen frame to its upper position, said roller means being disengageable with said screen frame when the flat portion of said roller means rotates into proximity of

- said screen and permitting said frame to return to the lower position,
- (e) an intermittently rotatable turret operatively mounted on said base means,
- (f) a plurality of article retaining means mounted on said turret and being sized to retain desired articles for printing,
- (g) means for feeding a supply of electroscopic ink to said screen when said article retaining means are aligned with said screen,
- (h) means for rotating said turret and moving said movable screen frame in pretimed relationship so that each one of said article retaining means becomes aligned with said screen,
- (i) and means for creating an electrostatic field between said screen and article retaining means so that ink will pass thru the open portions of the screen to the article retaining means.
3. An electrostatic printing apparatus comprising:
- (a) base means,
- (b) a movable screen frame operatively mounted on said base means and being shiftable between upper and lower positions during a printing cycle,
- (c) an electrostatic printing screen operatively associated with said screen frame and being movable therewith,
- (d) driving roller means operatively mounted on said base means and having an arcuate portion and a flat portion, said arcuate portion being engageable with said screen frame for moving said screen frame to its upper position said roller means being disengageable with said screen frame when the flat portion of said roller means rotates into proximity of said screen and permitting said frame to return to the lower position,
- (e) pneumatic damping means for breaking the movement of said screen frame as it returns to its lower position,
- (f) an intermittently rotatable turret operatively mounted on said base means,
- (g) a plurality of article retaining means mounted on said turret and being sized to retain desired articles for printing,
- (h) means for feeding a supply of electroscopic ink to said screen when said article retaining means are aligned with said screen,
- (i) means for rotating said turret and moving said movable screen frame in pretimed relationship so that each one of said article retaining means becomes aligned with said screen,
- (j) and means for creating an electrostatic field between said screen and article retaining means so that ink will pass through the open portions of the screen to the article retaining means,
4. An electrostatic printing apparatus comprising:
- (a) base means,
- (b) an intermittently rotatable turret operatively mounted on said base means,
- (c) a plurality of article retaining means mounted on said turret and being sized to retain desired articles for printing,
- (d) a pair of movable screen frames operatively mounted on said base means for oscillatable movement about an axis to first and second end positions and on opposite sides of said article retaining means so that the article retaining means are successively positioned between said screen frames,
- (e) electrostatic printing screens operatively associated with each of said screen frames and being movable therewith,
- (f) means for feeding a supply of electroscopic ink to said screens when said article retaining means are aligned with said screens,
- (g) means for rotating said turret and oscillating said screen frames in pretimed relationship so that each

- successive one of said article retaining means becomes aligned with said screens,
- (h) and means for creating an electrostatic field between said screens and article retaining means so that ink will pass through the open portions of the screens to the article retaining means.
5. A multicolor electrostatic printing apparatus comprising:
- (a) base means,
- (b) an intermittently rotatable turret operatively mounted on said base means,
- (c) a plurality of article retaining means mounted on said turret and being sized to retain desired articles for printing,
- (d) a pair of movable screen frames operatively mounted on said base means for oscillatable movement about an axis to first and second end positions and on opposite sides of said article retaining means so that the article retaining means are successively positioned between said screen frames,
- (e) electrostatic printing screens operatively associated with each of said screen frames and being movable therewith,
- (f) means for feeding a supply of electroscopic ink to said screens when said article retaining means are aligned with said screens,
- (g) means for rotating said turret and oscillating said screen frames in pretimed relationship so that each successive one of said article retaining means becomes aligned with said screens,
- (h) and means for creating an electrostatic field between said screens and article retaining means,
- (i) and means for feeding different colored electroscopic inks to each of said printing screens so that inks will pass through the open portions of the screens to the article retaining means and imprint a multicolor image thereon.
6. A multicolor electrostatic printing apparatus comprising:
- (a) base means,
- (b) a first continuously rotatable shaft operatively mounted on said base means,
- (c) an actuating wheel operatively mounted on said shaft and rotating through continuous 360° revolutions,
- (d) a second shaft operatively disposed in spaced relation to said first shaft,
- (e) a slot-wheel having a plurality of engageable slots operatively mounted on said second shaft and being intermittently rotatable,
- (f) an extended pin on said actuating wheel for engaging any of said slots on said slot-wheel and rotating the slot-wheel through fractional revolutions during each complete rotational movement of said actuating wheel,
- (g) a turret operatively connected to said slot-wheel and being rotatable therewith so that said turret is moved to successive positions,
- (h) a plurality of articles retaining means mounted on said turret and being sized to retain desired articles for printing,
- (i) a pair of movable screen frames operatively mounted on said base means on opposite sides of said article retaining means so that the article retaining means are successively positioned between said screen frames,
- (j) electrostatic printing screens operatively associated with each of said screen frames and being movable therewith,
- (k) means for feeding a supply of electroscopic ink to said screens when said article retaining means are aligned with said screens,
- (l) means for moving said movable screens simultaneously in opposite directions and in pretimed relationship to said turret so that each one of said article

- retaining means becomes aligned with one of said screens,
- (m) and means for creating an electrostatic field between said screens and article retaining means so that ink will pass through the open portions of the screen to the article retaining means.
7. An electrostatic printing apparatus comprising:
- base means,
  - a drive shaft operatively mounted on said base means,
  - a camming member operatively mounted on said drive shaft and being rotatable therewith, said camming member having an internal groove,
  - a movable screen frame operatively mounted on said base means and being shiftable between first and second positions during a printing cycle,
  - an electrostatic printing screen operatively associated with said screen frame and being movable therewith,
  - roller means operatively associated with said screen frame for riding in said camming groove and providing shifting movement to said screen frame so the screen frame moves between said first and second positions,
  - an intermittently rotatable turret operatively mounted on said base means,
  - a plurality of article retaining means mounted on said turret and being sized to retain desired articles for printing,
  - means for feeding a supply of electroscopic ink to said screen when said article retaining means are aligned with said screen,
  - means for rotating said turret and moving said movable screen frame in pretimed relationship so that each one of said article retaining means becomes aligned with said screen,
  - and means for creating an electrostatic field between said screen and article retaining means so that ink will pass through the open portions of the screen to the article retaining means.
8. An electrostatic printing apparatus comprising:
- base means,
  - a drive shaft operatively mounted on said base means,
  - a covered heart type camming member operatively mounted on said drive shaft and being rotatable therewith, said camming member having a somewhat heart-shaped internal groove,
  - a movable screen frame operatively mounted on said base means and being shiftable between first and second positions during a printing cycle,
  - an electrostatic printing screen operatively associated with said screen frame and being movable therewith,
  - roller means operatively associated with said screen frame for riding in said camming groove and providing shifting movement to said screen frame so the screen frame moves between said first and second positions, said groove being so shaped that said roller means will move in said slot for an angular distance of approximately 90° causing said screen frame to shift from the first to the second end position and said roller means will move in said slot for an angular distance of approximately 270° causing said screen frame to shift back to the first end position,
  - an intermittently rotatable turret operatively mounted on said base means,
  - a plurality of article retaining means mounted on said turret and being sized to retain desired articles for printing,
  - means for feeding a supply of electroscopic ink to said screen when said article retaining means are aligned with said screen,
  - means for rotating said turret and moving said movable screen frame in pretimed relationship so

- that each one of said article retaining means becomes aligned with said screen,
- (k) and means for creating an electrostatic field between said screen and article retaining means so that ink will pass through the open portions of the screen to the article retaining means.
9. An electrostatic printing apparatus comprising:
- base means,
  - a drive shaft operatively mounted on said base means,
  - a pair of covered heart type camming members operatively mounted on said drive shaft and being rotatable therewith, each of said camming members having a somewhat heart-shaped internal groove,
  - an intermittently rotatable turret operatively mounted on said base means,
  - a plurality of article retaining means mounted on said turret and being sized to retain desired articles for printing,
  - a pair of movable screen frames operatively mounted on said base means on opposite sides of said article retaining means so that the article retaining means are successively positioned between said screen frames,
  - electrostatic printing screens operatively associated with each of said screen frames and being movable therewith,
  - roller means operatively associated with each of said screen frames for riding in the camming grooves and providing shifting movement to said screen frames so that the screen frames move between said first and second positions, said grooves being so shaped that said roller means will move in said slots for an angular distance of approximately 90° causing said screen frame to shift from the first to the second end position and said roller means will move in said slots for an angular distance of approximately 270° causing said screen frames to shift back to the first end position, said camming members being 180° out of phase with each other so that each of said screen members shift in opposite directions,
  - means for feeding a supply of electroscopic ink to said screens when said article retaining means are aligned with said screens,
  - means for rotating said turret and moving said screen frames in pretimed relationship so that each successive one of said article retaining means becomes aligned with said screens,
  - and means for creating an electrostatic field between said screens and article retaining means so that ink will pass through the open portions of the screens to the article retaining means.
10. An electrostatic printing apparatus comprising:
- base means,
  - an oscillating screen frame operatively mounted on said base means and being shiftable between upper and lower positions during a printing cycle,
  - an electrostatic printing screen operatively associated with said screen frame and being movable therewith,
  - an intermittently rotatable turret operatively mounted on said base means,
  - a plurality of article retaining means mounted on said turret and being sized to retain desired articles having an annular side wall for printing,
  - means for rotating said turret and moving said movable screen frame in pretimed relationship so that each one of said article retaining means becomes aligned with said screen,
  - means associated with said last named means for rotating said article retaining means about an axis so that the side wall of the article tangentially approaches and departs from the screen when in alignment with said screen causing a continually changing line of closest approach to exist between the annular side wall of said article and said screen,

- (h) ink feeding means located at the line of closest approach between said screen and article for feeding a narrow band of electroscopic ink to said screen at the line of closest approach when said article retaining means are aligned with said screen, 5
- (i) and means for creating an electrostatic field between said screen and article retaining means so that ink will pass through the open portions of the screen to an article on said article retaining means.
- 11. An electrostatic printing apparatus comprising:** 10
- (a) base means,
- (b) an oscillating screen frame operatively mounted on said base means and being shiftable between upper and lower positions during a printing cycle,
- (c) an electrostatic printing screen operatively associated with said screen frame and being movable therewith, 15
- (d) an intermittently rotatable turret operatively mounted on said base means,
- (e) a plurality of article retaining means mounted on said turret and being sized to retain desired articles having an annular side wall for printing, 20
- (f) means for rotating said turret and moving said movable screen frame in pretimed relationship so that each one of said article retaining means becomes aligned with said screen, 25
- (g) means associated with said last named means for rotating said article retaining means about an axis so that the side wall of the article tangentially approaches and departs from the screen when in alignment with said screen causing a continually changing line of closest approach to exist between the annular side wall of said article and said screen, 30
- (h) ink feeding means located at the line of closest approach between said screen and article for feeding a narrow band of electroscopic ink to said screen at the line of closest approach when said article retaining means are aligned with said screen, 35
- (i) means associated with said ink feeding means to reduce the velocity of the ink particles to a substantially zero velocity before they reach the printing screen, 40
- (j) and means for creating an electrostatic field between said screen and article retaining means so that ink is propelled by the electrostatic field and passes through the open portions of the screen to the article on said article retaining means. 45
- 12. An electrostatic printing apparatus comprising:**
- (a) base means,
- (b) an oscillating screen frame operatively mounted on said base means and being shiftable between first and second end positions during a printing cycle, 50
- (c) an electrostatic printing screen operatively associated with said screen frame and being movable therewith,
- (d) a drive shaft operatively mounted on said base means, 55
- (e) means for intermittently rotating said drive shaft,
- (f) an intermittently rotatable turret operatively mounted on said drive shaft and being rotatable therewith, 60
- (g) a plurality of separate shaft-holding elements operatively mounted on said turret,
- (h) a plurality of mandrel shafts rotatably mounted in said shaft-holding elements, 65
- (i) an article retaining mandrel operatively mounted on the outer ends of each of said mandrel shafts and being sized to retain desired articles for printing,
- (j) a second shaft operatively mounted on said base means and being continuously rotatable, 70
- (k) first gear means operatively mounted on said second drive shaft,
- (l) second gear means operatively mounted on the inner ends of each of said mandrel shafts and being in meshing engagement with the first gear means 75

- for continuously rotating said mandrel shafts and mandrels about their central longitudinal axes,
- (m) means for feeding a supply of electroscopic ink to said screen when said article retaining means are aligned with said screen,
- (n) means for rotating said turret and moving said movable screen frame in pretimed relationship so that each one of said article retaining mandrels becomes aligned with said screen,
- (o) and means for creating an electrostatic field between said screen and article retaining means so that ink will pass through the open portions of the screen to an article on said article retaining means.
- 13. An electrostatic printing apparatus comprising:**
- (a) base means,
- (b) a first continuously rotatable shaft operatively mounted on said base means,
- (c) an actuating wheel operatively mounted on said shaft and rotating through continuous 360° revolutions,
- (d) a second shaft operatively disposed in spaced relation to said first shaft,
- (e) a slot-wheel having a plurality of engageable slots operatively mounted on said second shaft and being intermittently rotatable,
- (f) an extended pin on said actuating wheel for engaging any of said slots on said slot-wheel and rotating the slot-wheel through 90° arcs during 90° arcuate rotational movements of said actuating wheel,
- (g) a third shaft operatively mounted on said base means and being disposed in spaced relation to said second shaft,
- (h) a turret operatively mounted on said third shaft and being adapted for intermittent rotation,
- (i) a pair of pulley means operatively connected to said slot-wheel and to said turret,
- (j) belt means trained around said pair of pulley means for rotating said turret with said slot-wheel, each of said pulley means being sized so that when said slot-wheel is moved to successive positions which are spaced 90° apart, said turret is moved to successive equally spaced positions which are directly proportional to the 90° movement of said slot-wheel,
- (k) a plurality of article retaining means mounted on said turret and being sized to retain desired articles for printing,
- (l) an oscillating screen frame operatively mounted on said base means and being shiftable between first and second end positions during a printing cycle,
- (m) an electrostatic printing screen operatively associated with said screen frame and being movable therewith,
- (n) means for feeding a supply of electroscopic ink to said screen when said article retaining means are aligned with said screen,
- (o) means for moving said movable screen frame in pretimed relationship to the movement of said turret so that each one of said article retaining means becomes aligned with said screen,
- (p) and means for creating an electrostatic field between said screen and article retaining means so that ink will pass through the open portions of the screen to an article on said article retaining means.
- 14. An electrostatic printing apparatus comprising:**
- (a) base means,
- (b) a first shaft operatively mounted on said base means,
- (c) a movable screen frame operatively mounted on said first shaft and being shiftable between upper and lower positions about said first shaft during a printing cycle,
- (d) an electrostatic printing screen operatively associated with said screen frame and being movable therewith,
- (e) driving roller means operatively mounted on said

- base means and having an arcuate portion and a flat portion, said arcuate portion being engageable with said screen frame for moving said screen frame to its upper position said roller means being disengageable with said screen frame when the roller means rotates into proximity of said screen and permitting said frame to return to the lower position, 5
 (f) pneumatic damping means for breaking the movement of said screen frame as it returns to its lower position,
 (g) a second drive shaft operatively mounted on said base means,
 (h) means for intermittently rotating said second drive shaft,
 (i) an intermittently rotatable turret operatively mounted on said second drive shaft and being rotatable therewith, 15
 (j) a plurality of separate shaft holding elements operatively mounted on said turret,
 (k) a plurality of mandrel shafts rotatably mounted in said shaft holding elements,
 (l) an article retaining mandrel operatively mounted on the outer ends of each of said mandrel shafts and being sized to retain desired articles for printing, said articles having an annular side walls, 20
 (m) a third drive shaft operatively mounted on said base means and being continuously rotatable,
 (n) first gear means operatively mounted on said third drive shaft,
 (o) second gear means operatively mounted on the inner ends of each of said mandrel shafts and being in meshing engagement with the first gear means for continuously rotating said mandrel shafts and mandrels about their central longitudinal axes, 25
 (p) means for rotating said turret and moving said movable screen frame in pretimed relationship so that each one of said article retaining means becomes aligned with said screen,
 (q) means associated with said mandrels for positioning said article retaining mandrels so that they are rotated about an axis where the side wall of the article tangentially approaches and departs from the screen when in alignment with said screen causing a continually changing line of closest approach to exist between the annular side wall of said article and said screen, 30
 (r) ink feeding means located at the line of closest approach between said screen and article for feeding a narrow band of electroscopic ink to said screen at the line of closest approach when said article retaining means are aligned with said screen, 35
 (s) means associated with said ink feeding means to reduce the velocity of the ink particles to a substantially zero velocity before they reach the printing screen,
 (t) and means for creating an electrostatic field between said screen and article retaining means so that ink is propelled by the electrostatic field and passes through the open portions of the screen to the article on said article retaining means. 40
15. An electrostatic printing apparatus comprising:
 (a) base means,
 (b) a first drive shaft operatively mounted on said base means,
 (c) a pair of covered heart type camming members operatively mounted on said first drive shaft and being rotatable therewith, said camming member having a somewhat heart-shaped internal groove, 45
 (d) an oscillating screen frame operatively mounted on said base means and moving between first and second end positions during a printing cycle,
 (e) an electrostatic printing screen operatively associated with said screen frame and being movable therewith,
 (f) roller means operatively associated with said screen 50
 70
 75

- frame for riding in the camming grooves and providing shifting movement to said screen frames so that the screen frame moves between said first and second positions, said grooves being so shaped that said roller means will move in said slots for an angular distance of approximately 90° causing said screen frame to shift from the first to the second end position and said roller means will move said slot for an angular distance of approximately 270° causing said screen frame to shift back to the first end position,
 (g) an intermittently rotatable turret operatively mounted on said base means,
 (h) a plurality of article retaining means mounted on said turret and being sized to retain desired articles having an annular side wall for printing,
 (i) means for rotating said turret and moving said movable screen frame in pretimed relationship so that each one of said article retaining means becomes aligned with said screen,
 (j) means associated with said last named means for rotating said article retaining means about an axis so that the side wall of the article tangentially approaches and departs from the screen when in alignment with said screen causing a continually changing line of closest approach to exist between the annular side wall of said article and said screen,
 (k) ink feeding means located at the line of closest approach between said screen and article for feeding a narrow band of electroscopic ink to said screen at the line of closest approach when said article retaining means are aligned with said screen,
 (l) means associated with said ink feeding means to reduce the velocity of the ink particles to a substantially zero velocity before they reach the printing screen,
 (m) and means for creating an electrostatic field between said screen and article retaining means so that ink is propelled by the electrostatic field and passes through the open portions of the screen to the article on said article retaining means. 45
16. The method of electrostatically printing on articles which comprises:
 (a) disposing an article to be printed on a movable mandrel sized to retain the article,
 (b) positioning the article between a pair of oscillatable electrostatic printing screens,
 (c) feeding a quantity of electroscopic ink to the screens and enabling said ink to pass through the screens, 50
 (d) oscillating said screens about an axis in pretimed relationship and in opposite directions during the passage of ink through the screen to the article,
 (e) creating an electrostatic field between said article and said printing screen so electroscopic ink will pass through said screens to the article and imprint an image thereon,
 (f) introducing the article into a fixing media to harden the image thereon,
 (g) and ejecting the article from the mandrel. 55
17. The method of electrostatically printing on articles which comprises:
 (a) disposing an article to be printed on a movable mandrel sized to retain the article,
 (b) positioning the article between a pair of oscillatable electrostatic printing screens,
 (c) feeding a quantity of electroscopic ink to the screens and enabling said ink to pass through the screens, 60
 (d) oscillating said screens about an axis in pretimed relationship and in opposite directions during the passage of ink through the screen to the article,
 (e) rotating said article in pretimed relationship to said oscillating screens so that tangential approach and departure is maintained between said screens and the surfaces of said article,
 (f) creating an electrostatic field between said article 65
 70
 75

- and said printing screen so electroscopic ink will pass through said screens to the article and imprint an image thereon,
- (g) introducing the article into a fixing medium to harden the image thereon,
- (h) and ejecting the article from the mandrel,
18. The method of electrostatically printing on articles which comprises:
- (a) positioning an article in relation to a pair of movable electrostatic printing screens,
- (b) feeding a quantity of electroscopic ink to the screens and enabling said ink to pass through the screens,
- (c) oscillating said screens about an axis in pretimed relationship and in opposite directions during the passage of ink through the screens to the article,
- (d) rotating said article in pretimed relationship to said oscillating screens so that tangential approach and departure is maintained between said screens and the surface of said article thereby causing elemental lines of closest approach between said screens and the surface of said article,
- (e) locating the screens in spaced relation so that the elemental lines of closest approach on each side of said article are horizontally aligned on diametrically opposite sides of said article,
- (f) and creating an electrostatic field between said articles and said printing screen so electroscopic ink will pass through said screens to the article along the lines of elemental closest approach and imprint an image thereon.
19. The method of electrostatically multicolor printing on articles which comprises:
- (a) disposing an article to be printed on a movable mandrel sized to retain the article,
- (b) positioning the article in relation to a pair of oscillatable electrostatic printing screens,
- (c) feeding a quantity of electroscopic ink to the screens and enabling said ink to pass through the screens,
- (d) oscillating said screens about an axis in pretimed relationship and in opposite directions during the passage of ink through the screens to the article,
- (e) rotating said article in pretimed relationship to said oscillating screens so that tangential approach and departure is maintained between said screens and the surface of said article,
- (f) creating an electrostatic field between said article and each of said printing screens,
- (g) passing a different color electroscopic ink through each of said screens to the article to imprint a multi-color image thereon,
- (h) creating an electrostatic field between said article and said printing screens so electroscopic ink will

- pass through said screens to the article and imprint an image thereon,
- (i) introducing the article into a fixing media to harden the images thereon,
- (j) and ejecting the article from the mandrel.
20. The method of electrostatically printing on articles which comprises:
- (a) disposing an article to be printed on a movable mandrel sized to retain the article,
- (b) positioning the article between a pair of oscillatable electrostatic printing screens,
- (c) feeding a quantity of electroscopic ink to the screens and enabling said ink to pass through the screens,
- (d) oscillating said screens about an axis in pretimed relationship and in opposite directions during the passage of ink through the screens to the article,
- (e) rotating said article in pretimed relationship to said oscillating screens so that tangential approach and departure is maintained between said screens and the surface of said article thereby causing elemental lines of closest approach between said screens and the surface of said article,
- (f) locating the screens in spaced relation so that the elemental lines of closest approach on each side of said article are horizontally aligned on diametrically opposite sides of said article,
- (g) creating an electrostatic field between said article and said printing screen so electroscopic ink will pass through said screens to the article along the lines of elemental closest approach and imprint an image thereon,
- (h) introducing the article into a fixing medium to harden the image thereon,
- (i) and ejecting the article from the mandrel.

UNITED STATES PATENT OFFICE
CERTIFICATE OF CORRECTION

Patent No. 3,502,579

February 7, 1967

James W. Edwards et al.

It is hereby certified that error appears in the above numbered patent requiring correction and that the said Letters Patent should read corrected below.

Column 2, line 53, after "having" insert -- varying --; column 9, line 49, for "changed" read -- change --; column 14, line 66, strike out "be"; column 15, line 10, for "disposal" read -- disposable --; line 62, for "is it" read -- it is --; line 68, for "tangentially" read -- tangentially --; column 16 line 19, for "or" read -- of --; column 22, line 73, for "progresses" read -- progress --; column 23, line 38, after "side of" insert -- each of --; column 24, line 53, for "heat-shaped" read -- heart-shaped --; column 30, line 55, after "the manner" insert -- as --; column 33, line 17, for "thruh" read -- through --; line 72, for "screns" read -- screens --; column 34, line 59, for "articles" read -- article --; column 38, line 42, for "paced" read -- spaced --; column 39, line 25, for "walls" read -- wall --; column 40, line 8, after "will move" insert -- in --; column 41, lines 27 and 28, for "articles" read -- article --.

Signed and sealed this 22nd day of July 1969.
